FIG.1.

FIG.2.

FIG.3.

This is ordinary printing with characters of uniform width as in the usual typewriter, without justification of the right ends of the lines.

This is a sample of ordinary typing with book face type but without any attempt to justify the length of the lines of print so that the right hand ends are spaced the equidistant from the edge of the sheet.

This is an example of justified typing with book face type as accomplished by the "Electromatic" typewriter when equipped with the justifying and printing control devices of the present invention.

tion, New York, N. Y., a corporation of New
York

Application December 31, 1942, Serial No. 470,741

33 Claims. (Cl. 197—20)

This invention relates generally to improvements in printing machines adapting them for printing with bookface type in lines of justified length, and more specifically to devices for controlling the letter spacing functions of typewriting machines to provide for letter printing of variable widths and the justification of lines of such printing through the automatic variation of the spaces between the words of a line.

The main object of the invention is to provide controls in a typewriter to adapt it for work now done with settable type for book page printing and other ordinary printing work. In the usual typewriter, letter spacing is uniform to agree with a fixed type width, even though the effective parts of the type faces vary from the narrow I to the wide W. Printed matter is better in appearance and usefulness when the letters thereof are of variable size and differentially spaced.

An object of the invention is to provide the type bars of a typewriter with book-face type, and as the types of variable widths are impressed against the record material, the material is spaced differential distances with relation to the area needed by book-face print.

Another object of the invention is the provision of improved variable escapement mechanism controlled directly from the manipulative members of a typewriter or other form of printing machine with keyboard control. The manipulative members carry spacing control blocks of variable widths equal or proportional to the spaces required by the types selected through operation of the manipulative members. There is provided a direct mechanical connection between the paper carriage escapement and the spacing blocks on the manipulative members.

Another object of the invention is the provision of improved means for punching and reading a control tape as coordinated with operation of a typewriter. At the same time that the control tape is punched, justification factors are set up to determine the spacing to be effective between words when the control tape is later used to control operation of the machine which has made it. In other words, the typewriter is operated manually to select a line of words while the operator observes an indication of the extending length of the line and stops short to hyphenate or terminate word selection before a predetermined margin line is reached. While this is being done, the machine does not operate to print but it punches a control tape which is later fed through the machine and sensed to control auto-

matic printing of the characters selected by the operator, and at the same time, the spacing between words is so proportioned by the justification mechanism that the line ends at the predetermined point in alignment with the endings of all the other lines on the page as in book printing work. From the foregoing, it is obvious that during the initial or manual operation of the typewriter two controls are effected; through one control a tape is punched to provide means for automatically printing a line, and through the other control the justification mechanism is set up to predetermine the spacing between words during tape controlled automatic typing of the words, so that the length of the automatically printed line will be justified.

Another object is the provision of tape perforating and reading devices designed to allow an amount of slack between the punching and reading stations, so that the tape is punched to represent a line of print without any sensing or tape reading operations taking place; and then, after punching is completed, the slack portion of the control tape, which is representative of the desired line of print, is passed through the reading station while the punching station is ineffective. In this way, there are alternating operations of tape punching while setting up justification factors, and subsequent tape reading and typing while spacing according to the justification factors.

Another object of the invention is the provision of a tape control unit wherein a prepunched tape is used for a justified printing operation, that is, completely automatic. In this modification, the punching station is dispensed with and instead the tape is fed past two reading stations. The first station is provided for control of typewriter key operation without printing, merely for the purpose of setting up justification factors through the operation of the manipulative controls by the tape, just as though an operator were selecting a line of characters. After the extent of justification is determined for the line, the slack portion of the tape read by the first sensing station is then directed through the second sensing station to control the printing of a justified line.

Another object of the invention is the provision of devices for representing the characters in code on the control strip. A set of six combs is placed under the manipulative members of the typewriter and they are shifted in combinations according to the character or control key operated. These combs are also operated elec-

trically according to the readings of the tape to select automatic operation of the typewriter when the tape is the operating control medium. The combs control the perforation of a 6-place code for the selection of the various characters and symbols, and also the selection of the special control keys, such as the shift lock, shift release, indent space, back space, carriage return and automatic print keys. The tape forms a storing means for setting up the character selections in a form adapted for effecting automatic control.

Another object of the invention is the provision of devices for insuring that none of the keys can be partially operated. These devices automatically lock all stationary keys and pull down all keys which tend to be partially operated.

A further object of the invention is the provision of dual justification controls associated with each character selecting bar. Since the capital letter of a character is in many instances of a different width than the corresponding lower case letter, provision must be made for proper letter spacing operations under the two different conditions to take care of justification of capital letters selected by a shift as well as the spacing of the small letters.

A further object of the invention is the provision of justification mechanism adjusted according to the number of words to be printed in a line and further adjusted according to the space remaining at the end of the unjustified line. The mechanism is adapted to add together automatically these factors of the desired number of spaces and the remainder space and then proportion the total space into the number of spaces of such extent that the line finally printed will be justified.

Another object of the invention is the provision of controls permitting the use of the justifying devices without the tape punching and reading device. In other words, for the modified form of control, the keys of the typewriter are operated manually for the printing operation as well as for the initial justification setting operation. The tape may then be dispensed with because the operator repeats the setting of a line of characters; the first series of operations being made without printing, in order to prepare a justification setting that will later space the words to fill out the line, and the second series of character selecting operations being accomplished with justified printing.

A still further object of the invention is the provision of means adapting the book type printer for use with various kinds and styles of type. The type basket is made interchangeable and readily removable for quick changes from one kind of type to another. In some instances, when the type are changed, the newly selected type require different spacing and justifying controls than the type in the removed basket. In order to take care of such changed requirements in spacing, a justification spacing control bar is made removable. Therefore, each style of type can have a related basket of type and a special spacing control bar, both of which are readily placed in the machine by any operator.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view showing the typewriter on a cabinet holding the tape punching and reading mechanisms.

Fig. 2 is a detail view showing a sample of the tape as punched to control selection of various character printing keys and operating control keys.

Fig. 3 shows an example of the printed work sheet bearing unjustified printing sections and a justified printing section printed with book-face type.

Fig. 4 is a sectional elevation view taken through the keyboard, carriage and printing devices of the typewriter along line 4-4 of Fig. 1.

Fig. 5 is a front sectional elevation view taken along line 5-5 in Fig. 1 and showing the justifying control mechanism.

Fig. 5a is an elevation view taken along the line 5a-5a in Fig. 5.

Fig. 6 is a plan view partly of a section taken along line 6-6 in Fig. 5 and showing the justifying mechanism.

Fig. 6a is a sectional elevation view showing justification clutching devices operated by solenoids.

Fig. 7 is a sectional elevation view taken along line 7-7 in Fig. 5 and showing the center of the justifying mechanism.

Fig. 8 is another sectional elevation view taken along the line 8-8 in Fig. 5 and showing the right end of the justifying mechanism.

Fig. 9 is a detail view showing contact operating devices cooperating with a keyboard bail.

Fig. 10 is a detail view of the spacing stop cam and the shaft sectioned at line 10-10 in Fig. 5.

Fig. 10a is a bottom view of the stop cam shown in Fig. 10.

Fig. 11 is a front elevation view showing the line length and margin space indicator.

Fig. 12 is a diagram or cam chart of the various contours on the justification control cam.

Fig. 13 is an exploded front elevation view showing the key lever guide and the six code control combs for responding to and governing the selection of the various character and control keys.

Fig. 14 is a sectional view along line 14-14 of Fig. 1 of the tape perforating and reading unit.

Fig. 15 is a sectional elevation view along line 15-15 of Fig. 1 of another control unit provided with two tape reading devices for governing complete automatic operation under control of a prepared tape.

Fig. 16 is a sectional view through the tape feeding rollers taken along line 16-16 in Fig. 15.

Figs. 17 and 17a taken together form a wiring diagram of the electrical controls in the machine.

Fig. 18 is a side view of a removable type basket.

Fig. 19 is a perspective view of a removable letter space control bar.

The devices of the invention are embodied in a printing machine here shown as the well known typewriter named the "Electromatic." Since this machine is well known in the art and the mechanisms therein have been described in numerous patents, only a brief general description will be given, but such as will enable those skilled in the art to understand the present invention.

The type bars 23 (Fig. 4) are pivotally mounted on the usual segment 24 by means of a curved fulcrum wire 25. Each of the type bars is ordinarily locked in the position of Fig. 4 by means of toggle links 26. One of these toggle links, the

one which is pivoted to the type bar 23, is connected by a rod 27 to a sub-lever 28 pivoted on a fulcrum wire 29. The latter is supported on a frame 30 which is mounted in the framework comprising the side frames 22 and the base of the machine.

Pivotedly mounted on a pair of aligned rods 31 supported in the framework of the machine are cam units 32 connected by links like link 33, to the related sub-levers 28. Each cam unit has a cam 34 which, in the case of those intermediate levers 35 controlling the operation of the character type, have two lobes, as in Patents 1,777,055 and 2,200,767. Each lever 35 has an arm 35a integral therewith having a slotted connection to a trip lever 36 in the associated cam unit.

When any lever 35 is depressed, it operates the related trip lever 36 through the arm 35a, allowing the cam 34 of the associated cam unit 32 to rotate a slight amount just sufficient to cause the cam unit to be operatively engaged by the constantly rotating power roller 37. The lobe of the cam 34, in cooperation with the power roller 37, causes a cam unit 32 to be rocked in a clockwise or a counterclockwise direction, depending upon whether the operative cam unit is on the left hand rod 31 or the right hand rod, Fig. 4. This causes the associated link 33 to be drawn downwardly, thereby rocking the sub-lever 28 in a clockwise direction. Through the connections comprising the link 27 and the left hand toggle link 26, the type bar 23 associated with the depressed key is rocked in a counterclockwise direction to effect an impression of the type on the work sheet 21.

The carriage comprises end plates 38 (Figs. 4 and 5) integrally joined by a channel-shaped member 39 which is formed with two grooves in which ride the usual anti-friction trucks 40 supporting the carriage on the grooved front and rear rails 41, 42, respectively. The platen 43 is rotatably mounted on the carriage in the usual way. A novel escapement mechanism is provided comprising a rack 44 fastened to the bottom of channel 39, and a pinion 45 attached to a shaft 46 supported by a bearing bracket 47 and bearing plate 351 fastened to the right side frame 22, Fig. 5. The operation of shaft 46 for justified spacing control is described more fully herein-after.

Fastened to the bottom of channel 39 is a block 48 to which is attached one end of a metal tape 49 that is drawn around the usual spring drum 50 which serves to draw the carriage toward the left of the machine for letter spacing.

As shown in Fig. 1, the typewriter is mounted on a cabinet 51 containing two control units M and N for punching and reading a control tape 52, Fig. 2. The typebars 23 are equipped with book-face type, having as many widths as desired for a particular style and face, and the carriage is variably spaced in agreement therewith.

For the combined manual and automatic control of the machine the operator sets the width of page desired and then operates the keys for a line of words without printing them. A punch mechanism in unit M makes a perforated record of the selected words. As the keys are operated, an indicator moves relative to a scale and in accordance with the variable width of the character keys depressed, to apprise the operator when she approaches the selected right hand margin. Word space counting and justifying controls are set as the keys are operated for

5 a full line, just short of the selected line length. The operator then presses an auto print key which causes tape controlled typing of the line with variable spacing, and at the same time automatic justification takes place so that an even vertical right hand margin results.

10 For complete automatic control of the machine, a tape is prepunched with code punchings for each line and inserted into unit N. When called into operation, a first set of tape selected key operations serves to set up a justification factor without printing, and the following set of tape controlled operations cause typing of a line of justified length

15 A third fully manual type of control of the machine is used when the tape is dispensed with and each line is typed twice by hand; the first time without printing and the second time with justified printing. Before manual operation, switches are set to disable the tape punching and feeding devices.

20 An object of the invention is to provide means whereby the operator can store all the characters needed in the given line of text and at the same time have the width of those characters measured automatically so that the space between words can later be adjusted so that line justification results. The storing device provides the means whereby a line can be automatically typed after the justification factors have been 25 considered, so that the finished result resembles a page of text printed with settable type.

25 In the present instance, the means for storing data is in the form of the control tape 52, Fig. 2, 30 perforated in each of the positions with a combination of one or more of as many as six perforations. Through the use of code perforations, a compact record is formed to bear indications of the many character, sign and control key operations needed in the functioning of the improved typewriter.

35 The tape 52 is perforated under control of six combs A, B, C, D, E and F, Figs. 4 and 13, which 40 are located under a set of operating key levers 53 and slidably mounted on studs 54 extending from a slotted guide plate 55 fastened between the side frames. All the levers 53 are pivoted on a wire 45 56 attached to a frame member 57, and urged upward by springs 58 so that the front parts of the 50 levers are normally in the upper ends of slots 59, Fig. 13, in the plate 55. There is a guide slot 59 for each character or control key lever 53. Aligned with each slot 59 are six notches in the 55 six combs, with certain of the notches formed with cam faces such as faces 60, 61, 62 and 63, while other notches such as 64 and 65 are straight sided and without cam faces.

60 While the key levers 53 are raised, they are out of cooperation with the cam faces of the notches 65 in the combs. However, as soon as a key is depressed, one or more of the combs are shifted to the left, and contacts 66a-66f are closed to energize certain of six punch magnets which act to punch a combination of holes 67, Fig. 2, in the tape. As shown in Fig. 2, the hole positions bear a direct relationship to the presence of cam faces on the six combs. For example, the shift lock key lever 53 operates in the slot 59, Fig. 13, at the extreme left end of plate 55 and there cooperates with the cam faces 60, 61, 62 and 63 on combs A, B, D and F, respectively, to cause the code perforation of four holes 67, spaced as shown at the top of Fig. 2, in alignment with the designations A, B, D, F, denoting the relationship between the combs and the perforation positions.

In the same way, each of the other key levers, operates a combination of combs, and punches a combination of holes 67 to store datum representations on the tape 52.

At the left end of each comb, Fig. 13, a leaf spring 68 pushes against the comb to restore it so that the ends of slots 69 are held against the studs 54.

When an automatic printing operation is selected, certain of the combs A-F are locked in the normal position to prevent movement towards the left and thereby prevent depression of unselected keys 53. Other selected combs are pulled toward the left in a combination to select one particular key while locking other keys by placing the upper edges of the comb teeth under the keys.

The locking means includes a series of six crank latches 4 pivoted on stud 5 and urged by springs 8 into locking relation with notches 3 cut into the six combs A-F. However, a bail bar 10 normally holds all latches 4 out of notches 3 to free the combs for manual operation. Bar 10 is part of a bail 6 pivoted on a stud 11 and held clockwise by spring 9. Early in the selection of an automatic print cycle a magnet BM is energized and it acts to rock bail 6 in a counterclockwise direction and allows latches 4 to be rocked in the same direction by springs 8 to lock all combs. Attached to each of the six latches is a call wire 7 forming part of a fast acting solenoid for pulling the latch out of the notch. Six solenoids LS1-LS6 are arranged in a staggered formation to pull on the call wires 7 when energized. A combination of solenoids are energized in accordance with code perforations sensed in the record tape during automatic printing. Accordingly, one or more of the combs A-F are released so that they may be pulled to the left for key selection.

For the purpose of pulling a tape selected combination of combs toward the left there is associated with each comb A-F, Fig. 13, a slow acting solenoid CSI-CS6, the core 15 of which is attached to a hook slide 16 with an extending end engaging a projection 17 on the bottom of the related comb. Each solenoid CSI-CS6 is connected in parallel with a related solenoid LS1-LS6 to be energized therewith. The slide 16 is slotted to surround a stud 18 projecting from frame bar 55, Fig. 4. Stud 18 acts as a stop for the movement of the slide in both directions, for the slot is proportioned so that when the solenoid is energized, the slide and associated comb are pulled to the left far enough to place a wide notch opening such as notch 60 under a selected key and place locking shoulders under other keys. A combination of combs are so actuated to permit downward movement of only one key lever while all others are locked up. A spring 19 acts on slide 16 to permit restoration of the comb by spring 68 and movement towards the right whenever the solenoid is deenergized. The released comb is then free to follow toward the right to the home position as urged by leaf spring 68.

Between key levers 53, Fig. 4, and intermediate levers 35 are placed selective connections which may be broken to cause a non-print operation when the keys are operated for the initial half or preparation part of a line printing cycle. A complete cycle of operation comprises repeated operation of the same series of keys; first, to set up justification controls without printing, and second, to operate with printing. It is for this purpose that an abutment member 70 is pivoted at 71 on the top of each lever 35. Member 70 is

drawn by spring 73 to rest normally in the path of a lug 72 on the bottom of the related key lever 53. However, when manual printing control is not desired, a coupling magnet CM' is energized to swing an armature 74 to which is articulated a common rod 75 passing through slots 76 in the abutment members. Energization of magnet CM', moves rod 75 to the left, rocking members 70 counterclockwise and moving them away from lugs 72 so that motion of a lever 53 is not communicated to a related lever 35 to trip one of the cam units and cause typing operation.

Pivoted to the carriage return lever 35 is a special abutment member 78c which is shaped to be in position for normal operation directly under the lug 72 on the carriage return key lever 53. This special member 78c is also formed with a slot through which a hook rod 75' (Fig. 17, behind rod 75 in Fig. 4) projects for disabling control. Furthermore, the control by a magnet CM (Fig. 17a, behind magnet CM' in Fig. 4) and rod 75 over member 78c is the reverse of the control over members 70, because when members 70 are rocked to a position ineffective for printing, member 78c is allowed to stay in the effective position to enable carriage return control during the setting part of automatic operation, for reasons pointed out hereinafter.

A device is provided for closing contacts to initiate various control operations upon depression of any of the key levers 53 (Fig. 4). This device includes a bail pivoted on screws 80 secured to the side frames 22 and formed with a cross bar 81 (Fig. 11) underlying all of the key levers 53. Springs 79 pull upwardly on the sides of bar 81 to hold it normally against the underside of the levers. Attached to the right side frame 22 is a bracket 82 supporting a number of contacts 83, 84 and 85 with an insulation extension 86 pointing upward into contact with the lower side of cross bar 81. Upon depression of any key, the bail contacts 83 are closed to operate a means for locking the keys in a depressed position, and contacts 85 are also closed to initiate a paper feeding operation, while contacts 84 are opened to provide a control effective in connection with automatic printing.

Other contacts are operated under control of the same common bail 81. They are held on a bracket 87 fastened to the left side frame 22. These contacts 88 and 89 are fastened to insulation blocks on bracket 87 and cooperate with a pair of bell cranks 90 and 91 pivoted on the bracket. The bell cranks have adjustable screws 92 and 93 located under the bar 81 and spaced therefrom to delay the closure of contacts 88 and 89 until near the end of the key depression. These contacts are used to operate clutching devices to lock a justification setting bar after it has been shifted a differential distance depending on the key operated.

Other contacts are operated under control of the bail 81 by mechanical switch devices shown in Fig. 9. A bell crank 95 is pivoted at 96 on a standard 97 extending from the side of the machine and is in contact with the underside of the cross bar 81. A stationary bar 98 provides a fixed center for a switch lever 99 pivoted at 100 and provided with an over center spring 101 fastened between the end of lever 99 and the end of one arm bell crank 95. A strong spring 102 is drawn between the bell crank and the bar to hold the crank in constant cooperation with the cross bar 81. Upon depression of the bar due to the actuation of any of the keys, the bell crank 95

is rocked counterclockwise to move the left end of spring 101 past the dead center at 100 and thereby cause the spring to draw the lever 99 in a counterclockwise direction and suddenly strike against the insulation block 103 fastened to the lower blade of a pair of contacts 104. An insulation bar 105 cooperates with the center blade of other contacts 106 and 107 to close the former and open the latter as soon as the switch lever is operated. These contacts 104, 106 and 107 are part of the controls for effecting carriage escape-
ment with justified spacing.

A means is provided to pull down a partially depressed key lever and lock the other keys in the normal position to prevent any inaccuracies of operation due to improper manipulation of the keyboard. All the key levers 53 (Fig. 4) are formed with a pointed extension 110 facing forward from the lower edge. Cooperating with the extensions 110 on all of the keys is a wedge shaped common locking bar 111 pointed towards the rear and formed as part of a bail 114 pivoted on a shaft 112 held by the typewriter side frames. Attached to bail 114 is an armature extension 113 cooperating with a magnet LM. Whenever contacts 83 (Fig. 11) are closed, due to the depression of cross bar 81 by any of the key levers 53, Fig. 4, magnet LM is energized and bail 114 is rocked in a counterclockwise direction to shove locking bar 111 against the pointed extensions 110. Should any key lever 53 be in a partially depressed position when bar 111 is operated, the bar will serve to cam the lever down the remainder of the distance. All the other key levers will be locked in the normal raised position due to the insertion of the bar 111 under the extensions 110.

Provisions are made to operate the key levers 53 automatically independent of the operator. The combs A to F are operated and shifted in combinations according to the perforations in the tape and, when so positioned, align a series of openings such as 60, Fig. 13, for one of the key levers. In order to pull down any selected lever 53, Fig. 4, a series of springs 116 are attached to the front part of all key levers, a spring 116 being related to each lever. The lower ends of all springs 116 are attached to the cross bar 117 of a bail 118 pivoted on a shaft 119 fastened in the side frames. The bail is provided with a crank arm loosely pivoted on the plunger 120 of a solenoid OS. This operating solenoid OS is activated alternately with the setting of the combs so that after the desired key lever is selected, bail 118 is rocked in a clockwise direction to stretch all of the springs 116. One of the levers 53 will be free to move downward as urged by a spring 116 while the other springs will be extended due to the blocking of the related key levers by the combs. When the parts are in the normal position, springs 116 are either completely collapsed or weakened to such an extent that they fail to overcome the tension in springs 58 which urge the levers upward to the normal position.

As shown in Fig. 1, the cabinet 51 of the machine is provided with space for holding the punch unit M shown in Fig. 14. This unit is provided to perforate the tape 52 (Fig. 2) under control of the contacts 66a-f (Fig. 13) discussed with reference to the combs operated by the key levers. The punch unit is supported within a frame composed of a base 125 (Fig. 14) supporting a pair of side frames 126. At one end of the base is fastened a bracket 127 having a rotatable center 128 upon which the supply roll of tape 52 is mounted. A leaf spring 129 presses against the

bottom of the roll to hold the tape taut as it is being unwound. The tape is drawn upward over a guide roller 130 and threaded between a pair of blocks 131 and 132 fastened between side frames. Attached to the front end of block 131 is a punch guide and stripper plate 133 and directly beneath it is a die plate 134 attached to block 132. As the tape passes toward the right, it forms a loop 135 which is allowed to accumulate during the punching and space setting operations associated with a complete line of print.

A set of six magnets PM1-6 is provided, there being a punch control magnet for each of the code comb plates shown in Fig. 13. These magnets are fastened to the top of block 131 and each has a plunger 136 pivoted on a lever 137 fulcrumed at 138 on a bearing extension 139 fixed across the magnets. The levers 137 are guided by slots in a frame 138' fastened to the side of a punch guide 139' which is formed with openings for guiding the upper ends of a set of punch plungers 140. The lower ends of the six plungers 140 are guided in the stripper plate 133 and compression springs 141 are coiled between plate 133 and a shoulder on the plunger to hold the plunger in a normally raised position. However, when one or more of the magnets PM1-6 are energized, the corresponding levers 137 are rocked in a clockwise direction and press down the related plungers 140 to perforate the tape 52.

As soon as any of the plungers are operated, the keys are released in readiness for another setting operation. In order to perform this releasing operation, a pair of normally closed contacts 142 (Fig. 14) are placed in series with the key locking magnet LM (Fig. 4) and designed to be opened near the end of each punching stroke. Cooperating with the lower side of the six levers 137, Fig. 14, is a common bar 143 of a bail 144 pivoted on shaft 145 supported between the side frames 126. Attached to bail 144 is an over-center spring 146 fastened to an arm 147 pivoted at 148 on a bracket fastened to one of the side frames. When the bail 144 is in the normal position, it stretches spring 146 below center 148, so that arm 147 is held away from an insulation block 149 on the under side of the top blade of contacts 142. However, as soon as any of the punch levers 137 are operated, bail 144 is rocked in a counterclockwise direction and the left end of spring 146 is thrown above pivot 148 so that arm 147 is rocked suddenly in a counterclockwise direction to strike the underside of insulation block 149 and open contacts 142 to release the key levers. A guard plate 150 is fastened beneath the contact operating devices to prevent the bulging tape loop 135 from interfering therewith.

Alternating with the operation of the punches is the operation of feeding devices for advancing tape 52. A pair of feed rollers 151 and 152 are mounted on shafts loosely pivoted in the side frames 126. The lower roll 152 is provided with a ratchet gear 153 with which cooperates a pawl 154 pivoted on the end of an arm 155 fulcrumed at 156. Also fastened to shaft 156 is an armature 157 situated above a tape feeding control magnet TF1 and drawn upward by a spring 158. Whenever magnet TF1 is energized, armature 157 is rocked downward in a counterclockwise direction and pawl 154 is lowered to engage another tooth on ratchet 153, so that when the magnet is de-energized, the pawl turns feed roller 152 in a clockwise direction to advance the tape 52 and enlarge the loop 135.

The punch unit M is provided with tape read-

ing devices as well as tape perforating devices. After the perforating devices have operated to record a series of character representations on the tape and thereby formed a loop 185 of prepared tape, the operation of the punching devices is stopped while operation of the reading devices is initiated to control printing of the desired characters with justified spacing. The tape is drawn past a series of six reading control levers 160 by means of a pair of feed rollers 161 and 162, the operation of which is controlled by a magnet TF2. A lever 163 is pivoted at 164 above the feed control magnet TF2 and is formed with an armature extension 165 directly over the end of the magnet. At the other end of lever 163 is pivoted a pawl 166 cooperating with a ratchet wheel 167 fastened to feed roller 162. A spring 168 holds the lever 163 in a normally retracted position with armature 165 held away from the magnet. As soon as the magnet is energized, the lever is rocked in a clockwise direction and pawl 166 is carried upward to turn feed roller 162 in a counterclockwise direction and thereby draw tape 52 down past the sensing levers 160. The six sensing levers 160 are pivoted on a rod 170 fastened between the side frames. Each lever 160 is in the form of a bell crank with an upper end having a roller 171 pressing against the tape 52 at a point where a backing plate 172 is formed with openings, so that, should a perforation appear under the roller 171, lever 160 is permitted to rock in a counterclockwise direction as urged by a spring 173. When the lever so moves, it closes a related contact 174 which is wired in series with one of the solenoids CS (Fig. 13) for operating combinations of the combs A-F to select one of the character or control levers. As reading continues, the loop 185 is drawn smaller and smaller until it is eliminated altogether when the perforations relating to a full line have been read. Then the punch devices can again come into play to act upon another length of tape so that it represents data designed to control the reading unit for printing another line of characters.

At the same time that punching is being performed, a justification setting is established according to the widths of the various characters selected, the number of words in a line and the unused remainder of a predetermined line length. The setting for the various widths of the character types is taken directly from operating blocks *w* and *W* and secured to each character key lever 53 (Fig. 4). The block *w* is of a width equal to, or proportional to, the width of the lower case letter character selected by the related key, while the other block *W* is used to determine a justification setting when a capital or upper case character is selected. Cooperating with the blocks *w* and *W* are a horizontally fixed guiding comb 175 (Fig. 5) and a movable adjustment comb slide or justification bar 176. Both the guide and the slide are mounted on a ball comprising arms 177 and 178 rocking on a shaft 179 supported between side frames 22. The teeth of comb 175 are formed integral with the cross bar of the ball. Slide 176 is fashioned with a series of projecting prongs 180 extending upward in the path of the lower case blocks *w* and formed with sloping cam faces opposing the sloping faces formed on the lower ends of the blocks. As shown in Fig. 5, the prongs 180 are shaped to be moved toward the right when any one of the character key levers 53 is depressed.

The extensions on the guide comb 175 extend

upward alongside the left edges of the justification blocks *w* to support the key levers and prevent any sideward movement while slide 176 is being shoved toward the right by a block. The distance that the slide will be moved toward the right is dependent upon the width of the block *w*, which in turn is proportioned to correspond with the width of the type face selected by the key lever which bears the block. Guide 175 is cut out as at 181 to avoid cooperation with those key levers 53 dealing with special operations of the typewriter other than character or sign selection operations. Comb slide 176 moves on the ball as guided by a pair of pin and slot connections 182. The ends of guide comb 175 are formed with bottom flanges 183 to which the side arms 177 and 178 are secured to form the ball structure of which guide 175 is the cross bar.

Referring to Fig. 4, it is seen that the arm 177 is drawn against a stop 184 by means of a spring 185 which tends to hold the ball in the normal position wherein the lower case blocks *w* cooperate with the prongs 180.

Means is provided to rock the ball 175, 177, 178 in a clockwise direction so that prongs 180 are placed beneath the justification blocks *W* relating to the upper case letters. The shifting operation is accomplished by energization of a shift magnet SM which is secured to the frame and located directly beneath an armature extension 186 forming part of the side arm 177 of the ball. The ball is held adjusted in the clockwise direction as long as a shift key is locked depressed or whenever the tape reading device detects a combination of perforations corresponding to the selection of a shift operation.

The movement of slide 176 (Fig. 5) toward the right is communicated to a number of other justification setting slides, the main one being slide 187 which is shaped like a reclining H with a vertical cross member and a pair of horizontal upper and lower portions 188 and 189, respectively. A shoulder 190 formed on the right end of slide 176 cooperates with the vertical bar of setting member 187, so that all movement of the slide is imparted directly to the member so that it is moved toward the right a distance corresponding to the width of the type member selected. The upper portion 188 of member 187 is concerned with governing the spacing of the carriage for letter spacing and spaces between words. However, since the carriage is not operated during the initial justification setting portion of the control, it is believed well to explain carriage operation hereinafter along with the discussion of automatic printing.

The lower portion of member 187 exercises control over three different portions of the justification setting means. A bar 193 is adjusted to point out the amount of line length that has been used by any number of character selection operations. Another bar 194 is operated by member 187 and used as a contact closer whenever the member is released for restoration after the operation of the space key. The third member 195 is operated by member 187 to provide a setting for registering the unused remainder of a line length, and the said third member also acts as a carrier for a space counter that is advanced according to the number of words in the line.

Slides 193 and 194 are connected to an extension 196 of member 187 by clutch devices designed to enable these slides to partake of all movement of member 187 toward the right but to avoid any tendency to follow the member back when it is

restored toward the left. As shown in Figs. 5 and 6a, the extension 196 of member 187 is inserted into a clutch frame 191, the lower portion of which is cut out to hold a pair of spring pressed ball bearings, while holes in the upper portion guide a pair of plungers 197, 197' secured to ends of toggles, the upper ends of which are pivoted on studs 198 projecting from brackets 199. Both slides 193 and 194 have inner frictional faces cooperating with wedging clutch faces on extension 196, Fig. 6a. The two plungers 197 are adapted to press on slides 193, 194 to disengage them from extension 196. The centers of the toggles are articulated on plungers 200, 200' sliding in the cores of clutch solenoids CS7 and CS8. The energization of solenoid CS7 is timed so that while member 187 is moving toward the right, slide 193 remains clutched therewith and carried along to the right, after which the solenoid is energized and slide 193 is forced against the bottom of frame 191 and fixed with relation to the stationary frame of the machine. After member 187 is fully restored to the left, solenoid CS7 is deenergized and slide 193 again engages extension 196 to accompany its movement to the right. By many of such successive movements of slide 193 toward the right, there is accumulated an elapsed length of line which is equal to, or directly proportional to, the amount of space necessary for the letters and spaces of the selections made by the operator.

The right end of slide 193 approaches a settable contact 200' on an inwardly pointing adjustable arm 201 held in a selected position by a set screw tightened on a horizontal rod 202. As the slide approaches the arm which is set to correspond with a predetermined length of line, it is desired that the amount of unused space be indicated where the operator can watch it so as to determine when to hyphenate or terminate word selections and call the automatic printing devices into operation. For this purpose an indicator is provided and slide 193 is connected therewith by a tape. The left end of slide 193, Fig. 5, is attached to one end of a metal tape 203 which is drawn around a roller 204 extending from a bracket 205 secured to the left side frame 22. The tape is drawn around another roller 206 pivoted on a bracket 207 secured to the left frame. In order to change the direction of movement of a pointer on the tape 203, a third guiding roller 208 (Fig. 11) is provided at the right side of the machine. The tape is guided around this roller 208 and drawn over to the left where it is wound on a spring drum 209 pivoted on a bracket 210 secured to the left side frame. Attached to the tape 203, at a point normally near the spring drum at the left, is a pointer 211 projecting forward out of a front cover plate 231 and cooperating with a horizontal scale 212 fastened near the top of the cover plate. This scale 212 is calibrated and marked with degrees of line length in inches or divisions of pica, elite or any other style of type widths as desired. Cooperating with the divisions of the scale is a settable pointer 213 which can be moved along a fixed rod 214 and fastened in a position to indicate the desired length of line. The setting of this fixed pointer 213 corresponds with the setting of the contact arm 201 (Fig. 5) for establishing contact when the selected length of line has been used. Of course, movable pointer 211 will move toward the right (Fig. 11) and is drawn by the metallic tape 203 in proportion to the common movements of the slide 193, Fig. 5, member 187 and comb 176 which, it will be re-

membered, is moved directly by the cam blocks *w* and *V* on the various key levers. Thus, the indicator 211 will reveal the amount of movement of slide 193 as it is moved towards the right nearer 5 the settable contact arm 201.

During character selecting operations, and at the same time that slide 193 is moved toward the right, the other slide 194, Fig. 6a, will also be moved in the same direction and to the same extent. Solenoid CS8 controls the connection and disconnection of slide 194 relative to extension 196. However, when a space operation is selected, slide 193 is advanced while slide 194 is released and allowed to be moved back into the restored position and thereby operate contacts for effecting controls which are to be explained in connection with the circuit diagram.

Slides 193 and 194 are restored by means of devices clutched directly to the main operating shaft of the machine. One of such devices is shown in Fig. 5. There it is seen that attached to the left end of slide 193 is a metal tape or belt 215 drawn around a guide roller 216 pivoted on bracket 205. The belt is drawn downward around a guide roller 217 and around a rewind drum 218. The drum is formed with a clutch face 219 opposite a sliding clutch collar 220 splined to an operating gear 700, Fig. 5a, but movable toward the left to engage the clutch faces whenever a magnet RM is energized. Gear 700 meshes with another gear 701 which in turn cooperates with a gear 702 fastened to the operating shaft 305. The magnet RM cooperates with an armature lever 221 which is rocked to push collar 220 toward the left (Fig. 35) and connect drum 218 to the drive shaft, so that belt 215 is drawn downward and slide 193 is drawn toward the left whenever a restoring operation is selected.

Slide 194 is restored by similar rewind device 40 under control of a magnet RM'. In Fig. 5a it is seen that the belt 215' attached to the end of slide 194 is guided by rollers 217' before being wrapped around the spring rewind drum 218'. A normally disengaged clutch collar 220' is connected with the gear 701 and operated by an armature lever 221' and magnet RM' to effect rotation of the drum whenever restoration of slide 194 is to take place.

The third part adjusted by member 187, Fig. 5, is the space counting device holder 195 guided in a supporting and clutching frame 223. At its right end, holder 195 is formed with a channel guiding a vertical portion 224 of an L-shaped member 225 slidably mounted in the top of a block 226 having controls associated with word spacing operations as explained hereinafter.

Attention is now directed to the left side of holder 195 where it is seen to have an edge abutting against an extension 227 projecting to the right of member 187. This projection 227 serves to shove holder 195 and L member 225 toward the right to the same extent that member 187 is moved to the right under control of character key and the space key operation, but the primary purpose of extension 227 is to act as a stop for restoration of holder 195 after a final justification setting has been made.

Holder 195 is formed with an extension 230 encircling the right end (Fig. 5) of slide 193. The extension is in the form of a rectangular tube or socket lined with friction material and has adjustable pressure screws for applying the necessary amount of pressure to bind holder 195 into a driving connection with the slide. The friction socket is provided to enable holder 195 to move

toward the right along with slide 193 and yet be relatively free for positive movement toward the left for restoration. A spring drum and connecting tape, described hereinafter, urge holder 195 toward the left at all times and drive it positively in that direction to close control contacts after every space selecting operation. Although slide 193 remains in progressively advanced positions after the various selections of words of a line, it does not interfere with the restoration of holder 195 upon space selection because the socket connection 230 is an impositive one.

At the termination of character selections associated with a complete line, then slide 193 is moved to the right to abut against the settable contact arm 201, Fig. 8, and it is desired that holder 195, Fig. 5, partake of such movement to adjust the L-shaped justification member 224, 225. This movement is brought about through the socket connection 230 in the same manner as when movement is imparted during character selections. However, when contact is established between the end of slide 193 and the contact arm 201, a solenoid CS12 is energized and it acts to lock the holder 195 in the adjusted position. The solenoid CS12 is provided with a movable core 229 connected to a toggle and locking plunger 228 which are constructed and operated in the same manner as the locking devices of solenoids CS1 and CS8 already described. The extent of plunger movement of solenoid CS12 may be made greater than that of solenoid CS1 to prevent holder 195 from binding when slide 193 is depressed. The solenoid CS12 depresses holder 195 and locks it against the lower part of the fixed frame 223 fastened between the front and rear vertical frames of the justification unit. The holder is held in position while a reading is taken of the position of member 224 to determine the length of space to be allotted between words to justify an entire line.

Returning to consideration of member 187, Fig. 5, and the other parts associated therewith for setting a differential spacer to govern the spacing of a justified line, it is seen that beneath the upper portion 188 of member 187 is a stationary clutch plate 232 opposite a movable clutch plate 233 which is operated under the influence of a magnet CS13. This magnet is held in a case 234 fastened to the frame of the machine and is arranged in a vertical position so that when it is energized, plate 233 is pushed downward to pinch portion 188 between plates 232 and 233 so that spacing member 187 is held in adjusted position. When held in position, portion 188 provides a carriage escapement abutment as explained hereinafter. The timing of magnet CS13 is determined by the electrical controls explained hereinafter with reference to the wiring diagram.

Shortly before the initiation of printing, member 187 is adjusted into a differential position by means of connections that are normally ineffective but brought into play by the energization of a spacing control magnet SC. This magnet is fastened in a horizontal position against a cross bar 235 fixed longitudinally in the machine. Cooperating with the opposite end of magnet SC is an armature segment 236 pivoted on shaft 237 and normally drawn in a clockwise direction by a restoring spring 238. The lower end of sector 236 is in mesh with a rack slide 239 formed with a slot 240 encircling a pair of pins 241 projecting from the side of member 187. In the normal position of the parts, the left end of slot 240 is in

contact with the left stud 241 on member 187. In this way, member 187 is ready to partake of any movement of rack 239 towards the right while leaving the member 187 free to move towards the right independently of the spacing control rack and sector 236. However, when automatic spacing control is desired, magnet SC is energized and it then attracts the armature extension 242 on sector 236, rocking the sector in a counter-clockwise direction and pushing rack 239 and the connected member 187 towards the right until the right end of rack 239 abuts against the side of a differential space control cam 243. This cam was previously adjusted to vary the space between it and rack 239 according to the number of words in a line and the amount of unused space in a line so that when printing takes place, the spaces between words are extended to such a degree that the line is automatically justified. In other words, the space between the left face of cam 243 and the right end of rack 239 is varied and enlarged to such a degree by the adjustment of the cam during the initial selection cycle so that when the actual printing operation takes place and justified spacing operation is called for between words the spacing control will be called into operation by magnet SC and the amount of space will be determined by cam 243.

Also associated with member 187 is an indenting control for starting certain lines of print, such as the first line of a paragraph, a further distance from the left sheet edge than the usual beginning point of lines of print. These indenting devices are associated with the lower portion 189 of member 187. Portion 189 is cut out with a horizontal slot 244 sliding on studs 245 projecting from a stationary part of the machine. Slidably secured to portion 189 by means of pin and slot connections 246 is a rack slide 247 formed with teeth in mesh with the teeth on a sector 248 pivoted on a stud 249. A spring 250 urges the sector in a counterclockwise direction against a stop 251, and rack 247 is held in position towards the left wherein pin and slot connections 246 allow free movement of member 187 towards the right without interfering with the indenting controls. The amount of indented space desired is set up by means of a stop arm 252 fastened to a collar 253 which carries a set screw and is keyed to a rod 254 extending transversely across the machine. The distance that the first word of a paragraph is indented inside the margin of a sheet is determined by the space between the right end of rack 247 and the selected position of arm 252 as determined by the operator before he fastens the collar 253 to the stationary shaft 254. When the indenting control is desired, a control magnet IM is energized and attracts an armature block 255 formed as part of the sector 248. The sector is then rocked in a clockwise direction and carries along therewith rack 247 and member 187 which move towards the right until rack 247 strikes against arm 252. The resulting position of member 187 and portion 188 provides an abutment for limiting the movement of the carriage to the desired indented position.

Throughout the foregoing section of the description, reference is made to the movement of the various parts 176, 193, 194, 187 and 195 toward the right (Fig. 5) whenever the keys are manually operated. It is to be noted that the keys causing such operation are the character selecting keys and the space key, while the other control keys such as shift lock key, shift release key, carriage return key and automatic print key

do not cause movement of the various parts because they are not provided with operating blocks *w* and *W* and, therefore, have no means for initiating movement of the parts through comb 176. Although the control keys do not effect operation of the justification setting mechanism, they do operate the combs shown in Fig. 13 to set up control for perforating code representations in the record tape, so that the corresponding operations can be automatically selected when the machine is controlled by the tape.

Operation of the space key bar *S* (Fig. 4) calls into play various devices associated with the justifying control. Operation of this bar is used to restore some of the parts shown in Fig. 5; for example, slide 194, member 187 and holder 195 are restored upon each space key operation. Then, too, spacing operations are an index to the number of words in the line and are used to operate a space counting stop which later determines the extent of added justification space to be employed in enlarging the spaces between the words to fill out a line.

Turning back to Fig. 4, it is seen that the space bar *S* carries a rod 260 which cooperates with an insulation stud 261 projecting above a series of space control contacts 262, 262' and 263. These contacts are supported on insulation brackets secured to the front wall of the case. When the space bar is depressed, certain of the contacts are closed and others are opened to effect the various controls in different parts of the machine as noted hereinafter.

One control effected is the restoration of bar 194 due to the energization of magnet RM', Fig. 5a. Clutch 220' is closed by magnet RM' to draw down the metal tape 215' and pull the slide 194 to the left, Fig. 5, the clamp 197 being normally idle and thus permitting the slide to be restored despite the frictional drag encountered against the side of extension 196.

Limiting stops are provided for both slides 193 and 194 to hold them when they reach the normal restored position. When the slide 194 reaches the normal position at the left, it operates contacts to deenergize magnet RM' and thereby release slide 194 so that it can be held in the restored position.

At the same time that slide 194 is being restored, other clutch connections are established to restore slide 195. This is taken care of by the energization of a magnet RM¹, Fig. 6, which is mounted horizontally near the right end of the machine. As shown in Figs. 5 and 8, an armature lever 264 is pivoted on a bearing bracket 265 attached to the right wall 266 at the end of the case. The lower end of lever 264 straddles a clutch collar 267, Fig. 5, keyed to a drive shaft 268 constantly rotating while the machine is in operation. Alongside collar 267 is a drum 269 loosely mounted on the shaft and carrying one end of a metallic restoring tape 270. The tape passes upward between a pair of guide rollers 271 and is then drawn horizontally over another roller 272 near the top 273 of the extended case. Tape 270 is drawn around two other rollers 274 and 275 after which it is attached at 276 to the top of slide member 195. Whenever magnet RM¹ is energized, due to depression of the space bar, lever 264 is rocked in a counterclockwise direction (Fig. 5) and collar 267 is pressed into clutching relation with drum 269 and the drum is driven in a clockwise direction (Fig. 8) to draw the tape 270 downward and act upon the slide 195 (Fig. 5), so that it is drawn towards the left

and back to the normal position, after which the magnet is deenergized.

Every time the space bar is operated, a magnet SCI is energized to advance the L-shaped member 224, 225 with relation to a justification setting cam. Magnet SCI is secured to the frame of the machine and beneath it is pivoted an arm 277 on a rod 278. Pivoted at 279 on the free end of arm 277 is a stepping pawl 280 cooperating with a vertical rack 281 attached to the block 226 through which slides the horizontal lower leg 225 of member 224. The pawl is normally out of cooperation with rack 281, but another pawl 282 is normally engaged for holding and is drawn into cooperation with a second set of ratchet teeth on the opposite side of the rack by means of a spring 283. Cooperating with the top of the stepping pawl 280 is a stud 284 which is so located that it cams the pawl into cooperation with the rack whenever magnet SCI is energized. A spring 285 holds the arm 277 normally retracted against stop 286, but this spring is overcome when the magnet is energized and arm 277 is rocked in a counterclockwise direction, whereupon pawl 280 engages rack 281 and lifts it one step wherein it is held by the pawl 282. Pawl 280 is disengaged due to the restoration of the parts by spring 285 when magnet SCI becomes deenergized. Rack 281 is guided for movement in a vertical direction by means of a channel 290 fixed to the frame of the machine. Attached to the lower end of the rack is a spring 291 which tends to restore the rack but it is prevented from doing so as long as the holding pawl 282 remains engaged with the side of the rack. After a line has been printed, pawl 282 is automatically thrown out by means of a magnet RM2 which rocks the pawl in a clockwise direction against the tension of spring 283.

The upper end of setting member 224 is normally so spaced with relation to a justifying cam disk 292 that the first upward step of rack 281 will not bring the end of the member into engagement with the disk. This space is provided because it is necessary to divide the distance that the line is short by one space less than the number of words in the line to be typed.

From the foregoing, it is evident that the top end of member 224 is advanced upward into the path of ridges on disk 292 to an extent dependent upon the number of spaces in the line. This member also receives movement in the other horizontal direction due to operation of holder 195 toward the right to an extent determined by the remainder of unused space in a line. As a result of both movements, the top end of member 224 is advanced obliquely across the path of the cam faces or ridges 343 on disk 292 so that when the cam disk is later operated, it will be obstructed and come to rest at a differential position determined by both factors represented by the position of the member 224.

The movement of the pointer 211 to the right (Fig. 11) relative to the scale 212 shows the operator when he is approaching the end of the space allotted for the line by the adjustment of pointer 213. Before the operator reaches the end of this limit, he stops at the end of a complete word or hyphenates the word. In either case, he then depresses the space bar and following this the automatic print key to call into operation, control of the machine by the perforated tape for automatic printing as justi-

fied by the devices set up during manual operation.

Before going further into the description of the automatic printing and justifying controls, it is believed well to describe the driving connections from the main shaft of the "electromatic" to the additional mechanism at the right in Figs. 5 and 6, and between front and rear frames 301, 302. Near the bottom of Fig. 5, it is seen that the main drive shaft 37' passes into a housing 303 containing the usual "Electromatic" carriage return mechanism shown in greater detail in U. S. Patent 1,753,450. The right end of shaft 37' is tapped and a pair of lock nuts 304 cooperate with threads on an extension shaft 305 to lock it onto the main shaft. Shaft 305 extends toward the right and is supported by a bearing on the right frame 266. Attached to shaft 305 is a gear 306 in mesh with an idler gear 307 (Fig. 8) which in turn operates another gear 308 fastened to the short shaft 268 already mentioned. An auxiliary supporting frame 309 (Fig. 5) is fastened between the front and rear plates 301, 302 to provide a bearing for one end of shaft 268 as well as a bearing for another short shaft 310 upon which the idler gear 307 is loosely mounted. Attached to gear 308, Fig. 8, and shaft 268 is a pulley 311 carrying a belt 312 which is wrapped around another pulley 313 fastened to a long collar 314 (Fig. 5) loosely mounted on a horizontal shaft 315 supported between fixed cross bars 316 and 317. This shaft 315 is adjusted to locate the justifying cams 292 and 243 in positions to determine spacing between words, as described more fully hereinafter.

Depression of the special auto print key at the extreme right side of the machine, results in a number of special operations initiated by contacts closed by the key. One of such operations is designed to move the bar 193 and space control member 195 toward the right (Fig. 5) a distance equal to the unused space between the last letter of the last word and the predetermined end of the line, minus the usual word spacing distance. It will be remembered that, after the last printing operation at the end of a line, the space key is operated before the auto print key. This is done to restore many of the parts so that they are in correct position to start the justifying control. For example, member 195 is restored so that upon depression of the auto print key it will start from the normal position and be moved towards the right a differential distance. Magnet RM5 (Figs. 5 and 8) controls clutch devices for attaching member 195 to the driving means, in order that it will be drawn positively toward the right a differential amount. Cooperating with magnet RM5 held on a support 321 is an armature lever 322 pivoted at 323 on a bracket extending from the right side plate 266. The lower end of lever 322 is formed as a yoke embracing a clutch collar 324 slidably mounted on, and keyed to, the extension shaft 305 which rotates continuously during the operation of the machine. Alongside collar 324 is a drum 325 loosely pivoted on shaft 305. The left side of drum 325 (Fig. 5) is provided with a friction face designed to cooperate with the friction material on collar 324 when the two are brought into cooperation. Wrapped around drum 325 is a metal tape or belt 326 which is led upward between a pair of guid rollers 327 (Fig. 8) and drawn around another roller 328 mounted on a bracket 329 fastened to the end plate 266. Tape 326 is attached to the right end of slide 193.

From the connections already described, it is evident that when magnet RM5 is energized, armature lever 322 will be rocked in a counter-clockwise direction (Fig. 5) and drum 326 will be connected to drive shaft 305, so that it will rotate in a clockwise direction (Fig. 8) and draw down the tape 326 and move slide 193 toward the right (Fig. 5). At the time this happens, holder 195 is connected to slide 193 and partakes of the movement. It will be remembered that slide 193 is advanced progressively toward the right throughout all manual operations of the machine for selecting characters and also operated along with spacing between words. Therefore, slide 193 starts to move from a position one space to the right of the last selected character space, and the movement taken up as an incident to the initiation of automatic printing is a movement which carries it from the last selected position over to the stop 201 located for a predetermined length of line.

When slide 193 touches the settable stop 201, a contact is closed and a circuit established through the clutching solenoid CS12. This energized coil then acts to clamp holder 195 in the adjusted position where it is held during the automatic printing of the line. At the same time, magnet RM5 is deenergized to release the slide and the holder in the adjusted position. Since member 224 is carried along with slide 195 toward the right a differential amount, and since the same part is elevated an amount commensurate with the number of spacing operations, it is positioned in readiness to cooperate with, and govern 35 the setting of, the justifying control disk or cam 292.

The control cam 292 is released for operation and connected to the operating means through the energization of a pair of magnets 334 and 335 (Fig. 5) called into operation by relays activated upon operation of the auto print key. Cooperating with magnet 334 is an armature crank 336 pivoted at 337 and having an arm projecting into the path of a lug 338 formed on the side of the control cam 292. Crank 336 cooperates with lug 338 to hold the cam in the normal position shown in Fig. 7 wherein a notch 339 in the cam is opposite the normal position of the top of the L-shaped member 224. However, when magnet 334 is energized, crank 336 is rocked in a counter-clockwise direction (Fig. 5) so that the horizontal arm of the crank is lifted out of the path of lug 338, and cam 292 is free to turn in a counter-clockwise direction (Fig. 7). Concurrent with the release of the cam, magnet 335 (Fig. 5) acts to rock an armature lever 340 in a counterclockwise direction about a pivot 341. The lower end of lever 340 cooperates with a clutch collar 342 slidably mounted on shaft 315 and keyed thereon. When collar 342 is moved to the right, it encounters a frictional disk on the left end of sleeve 314 which, it will be remembered, is constantly rotating because it is connected to the main operating means by belt 312. When the clutch connection is established, the justification control cam 292 is rocked so that the projecting ledges thereon are moved toward the upper abutment end of member 224. A developed formation of the ledges on cam 292 is shown in Fig. 12 where it is seen that the ledges 343 converge to a point that is the origin of all ledges and then branch out in increasing thicknesses as they wind their way around the cam to the end 344 (Fig. 7) which marks the largest degree of justification possible for various numbers of words in a line. The de-

gree of movement of cam 292 is determined by the placement of stopping member 224 which, it will be recalled, is in turn dependent upon the number of spaces in a line and the extent of unused space at the end of the line before justification.

The movement of cam 292 is imparted to the space control cam 243 which is also attached to shaft 315. It is pointed out hereinbefore that space cam 243 has a slanting circular formation 346 adapted to be spaced differentially away from the right end of spacing slide 239. A bottom view of cam 243 in Fig. 10a shows that the cam is formed with a slanted spiral face, the highest point of which is removed from the end of slide 239 a distance proportioned to or about equal the usual word space. However, when automatic justified operation is selected, the cam is rotated counterclockwise to retract the slanted cam surface 346 differentially and vary the stopping point found by movement of slide 239, thereby forming an adjustable control for the movement of the spacing slide.

From the foregoing it will be apparent that early in automatic printing control operation, when the spacing control magnet SC (Fig. 5) is energized, the distance that the spacing extension 188 is moved to the right will depend upon the point at which slide 239 is obstructed by the cam face 346 on space cam 243, and that in turn will be dependent upon the positions of cams 243 and 292 which are determined by the position of stop 224 predetermined by the number of spaces and unused line length found during manual operation.

Magnet coils 334 and 335 are held energized until the justifying control cam 292 is positioned. The holding operation is accomplished by means of a delayed action control including a time delay relay which opens contacts to deenergize the magnets. A means is also provided to hold control cam 292 in adjusted position. A stationary friction disk 347 surrounds shaft 315 adjacent collar 342, but is free from movement with the shaft and instead is secured to the frame of the machine. When magnet 335 is deenergized and collar 342 moves away from the driving tube 314, a spring 348 forces the keyed collar 342 into contact with the stationary friction disk 347, thereby holding the connected cam 292 in the adjusted position. Disk 347 may be dispensed with if a frictional relation is maintained between shaft 315 and cam 292. The cam is later restored by reenergization of magnet 335 and engagement of the clutch to 314 until the lug 338 strikes crank 336.

Other contacts are operated by the automatic print key to cause an advance movement of the perforated tape 52 (Fig. 14). The contacts are in series with the feeding control magnet TF2 which acts, as explained hereinbefore, to pull the tape past the sensing rollers 171. The tape is advanced far enough to bring the first line of perforations under the sensing levers 160. The distance between the punches and the sensing position is proportioned so that after perforating operations are terminated, the sensing operations can be initiated to take a reading of the first series of combination perforations. When the first line of perforations is sensed, one or more of the levers 160 will rock in a counterclockwise direction to close certain of the contacts 174. These contacts are in series with the solenoids LS1 to LS6 and CS1 to CS6 (Fig. 13), controlling the movements of the combs A to F into key selecting positions.

At the same time that the automatic print key operates to initiate tape feeding and comb adjustment, it operates other electrical controls for establishing connections between the key levers

5 53 (Fig. 4) and the print control levers 35. Magnet CM' is deenergized to allow the interposer arms 70 to be pulled over toward the right, as shown, into an effective position under the lugs 72 on the key levers 53. Then, when the springs 10 116 are pulled down and a lever 53 follows along therewith, connection is established through a lug 72 and an interposer 70 so that an operating lever 35 is also depressed and the related cam unit 34 is released to cooperate with the power 15 roller 37 for typing.

Behind magnet CM' is a similar magnet CM for operating the interposer 75c which is associated with the key lever 53 and an operating lever 35' (Fig. 17, behind lever 35 in Fig. 4) for the carriage return function. During complete manual operation of the machine it is desired that all keys be effective and therefore all interposers 70 and 75c are positioned under the key lugs 72 as shown in Fig. 4. This is possible because both 20 control magnets CM and CM' are deenergized at the time, magnet CM being normally deenergized and magnet CM' being disabled by a switch.

However, when partly automatic or completely automatic control is selected by closure of all of 30 the manual switches and selection of tape control, the magnets CM and CM' are conditioned for reversal of control; i. e., when the carriage return interposer is effective, the character key interposers are ineffective, and vice versa. Magnet 35 CM' becomes a normally energized magnet for pulling the interposers 70 to the ineffective position. This is done to allow preliminary key operation for the justification setting without printing, when units M, Fig. 14, or N, Fig. 15, are being 40 used. At the same time, magnet CM is deenergized so that the carriage return key remains effective. For the second part of such automatic control cycles (i. e., the part for printing under tape control as initiated by operation of the auto 45 print key) the magnet CM is energized and opens contacts in series with the magnet CM' to disable it. The result is that interposers 70 are spring pulled to an effective position for printing while interposer 75c is pulled by magnet CM to an ineffective position. Thus, automatic printing is possible while the carriage return key is made ineffective for reasons pointed out hereinafter.

Solenoid OS is also made effective when the automatic print key is depressed. This solenoid 55 serves to actuate the bail bar 117 to which the springs 116 are attached, so that they are pulled down to urge all key levers 53 into an operated condition. However, since the combs A-F are adjusted in accordance with the first set of perforations sensed in the tape, they will provide an opening for only one of the key levers and that is the one previously operated by the first manual selection for the line of print.

The related type member 23 is operated to cause 65 a printing impression at the beginning of the line. As the key is operated, the common bail 81 (Fig. 9) is depressed and, near the end of the key operation, the contact operating lever 99 is snapped into operation to cause closure of contacts 104. These contacts are in series with controls for the carriage escapement device which is operated after the type bar has struck the platen. The carriage escapement magnet CE (Fig. 4) is in 70 series with contacts 104 and energized thereby to control the operation of clutches for connecting

the carriage to the means for moving it differentially according to the width of the type face related to the key depressed. It is mentioned hereinbefore that a rack 44 is secured to carriage frame 39 and that this rack is in mesh with a gear 45 attached to shaft 46. Also mounted on shaft 46 is a clutch collar 350 slideable on the shaft but keyed thereto to maintain the angular relation with gear 45. This collar 350 is normally in frictional contact with a stationary bar 351 fixed to the frame of the machine and thereby maintains the carriage in any adjusted position. On the opposite side of frame 351 is another clutch disk 352 attached to shaft 46. This disk 352 is hollowed out to act as a bearing for one end of an axially aligned shaft 46', the other end of which is supported by bracket 47' near the right end of the shaft. Alongside disk 352 is a movable clutch collar 353 keyed to shaft 46' and movable into cooperation with disk 352 to connect gear 45 with escapement control shaft 46'. However, the clutch collar 353 is held normally ineffective by being separated from disk 352 while the other clutch 350 holds the carriage stationary. When the escapement movement is to be made, the clutches reverse their positions to free the escapement shaft 46 from the stationary frame and connect it with the adjustable shaft 46' which is rotated differentially in a manner about to be explained.

Referring to Fig. 5, it is seen that a gear 355 is attached to the front end of shaft 46'. The gear is in mesh with a rack 356 supported by pin and slot connections 354. The right end of rack 356 normally abuts against the left end of portion 188 on the justifying control member 187, the setting of which has been explained hereinbefore. Therefore, when the automatically selected key lever 53 is drawn downward, the extension block *w* thereon moves the slide 176 and this in turn moves the member 187 and portion 188 toward the right a distance equal to the width of carriage escapement desired. The rack 356 normally does not tend to move toward the right to abut against the displaced portion 188, because the cooperating gear 355 is normally tending to rock in a clockwise direction as urged by a spring 357 attached to a stop arm 358 fastened to shaft 46'. This stop arm 358 normally cooperates with a block 359 extending from the side of fixed bracket 47. As long as the clutch 353, Fig. 4, is separated from the shaft 46, the spring 357 is effective to keep rack 356 and shaft 46' in a normal position. However, as soon as clutch 350 is released and clutch 353 is operated, shaft 46' is connected to shaft 46, and then the entire mechanism comes under the influence of spring drum 50 (Fig. 4) which is tending to move the carriage toward the left. The force exerted by the spring drum overcomes spring 351 (Fig. 5) and urges gear 355 in a counterclockwise direction to drive rack 356 toward the right to a differential extent until the right end of the rack abuts against the left end of extension 188 on the escapement control member 187.

It is evident that by means of the connections described, directly after automatic printing of a character, the carriage is governed to escape a variable extent commensurate with the width of the printed character. The carriage is held in the escaped position when the clutches reverse their condition, so that collar 350 (Fig. 4) is again drawn into cooperation with the stationary frame 351, while the other collar 353 is separated from disk 352 and shaft 46.

As soon as collar 353 is separated from disk 352, the rack 356 (Fig. 5) is free to snap back into the normal position as urged by spring 357. Shaft 46' is rocked clockwise until stop arm 358

strikes the block 359.

The carriage escapement magnet CE (Fig. 4) operates the connections for first closing clutch 352, 353 and then opening clutch 350. Pivoted above the magnet CE on center 360 is an armature lever 361 with a vertical arm having a pin and slot connection 362 to a horizontal link 363 slideably mounted on the frame 22. Connected to link 363 are a pair of clutch operating levers 364 and 365 pivoted at 366 and 367, respectively. A spring 368 tends to rock lever 365 in a counterclockwise direction and force the closure of clutch 353. However, it is prevented from doing so by a spring 369 which tends to hold the armature lever 361 in the normal position. However, when magnet CE is energized, lever 361 is rocked in a clockwise direction against an adjustable stop 370, and link 363 is moved toward the right, and then spring 368 is permitted to operate clutch lever 365 to shift clutch collar 353 into contact with disk 352.

Shortly after clutch 353 is operated, the end of a slot 371 comes into contact with a pin on the lower end of clutch lever 364 and this lever is then rocked counterclockwise to shift collar 350 away from the frame 351. The sequence of operation is arranged so that the carriage is connected with the variable spacing mechanism before it is disconnected from the stationary frame 351. A spring 372 is attached to clutch lever 364 and tends to shift the collar 350 into the normal holding position. When magnet CE is deenergized, the link 363 is released for movement toward the left and spring 372 acts first to position clutch collar 350 to lock the carriage in the escaped position before collar 353 is separated from disk 352 to allow the variable positioning mechanism to restore.

Cooperating with the end of armature lever 361 (Fig. 4) is an insulation block 374 secured to the top blade of a pair of contacts 375. These contacts are closed early in any carriage escapement cycle to establish a circuit through the clutch solenoid CS13 (Fig. 5). The solenoid operates to clamp or lock member 187 and portion 188 in the adjusted position so that it will not shift when rack 356 strikes the end of 188 with the weight of the carriage behind the rack.

When the carriage escapement magnet CE is energized, another time delay relay is also energized. This relay is adjusted so that it will provide an interval of lag equal to the time necessary for the carriage to escape a maximum distance required at any time. When the relay acts, it breaks the circuit to the carriage escapement magnet CE which then allows reclutching of the carriage to the frame and declutching from the variable escapement mechanism. The electrical control of the time delay relay is explained further hereinafter with reference to the wiring diagram.

The deenergization of magnet CE serves to break contact 375 and render solenoid CS13 (Fig. 5) ineffective and in this way releases member 187, so that it is ready for another character setting operation. The time delay relay will be held energized until the contacts 106 (Fig. 9) are opened due to the restoring of the selected key lever. The combs A-F are released to move toward the right (Fig. 13) into the normal position due to the deenergization of the selected sole-

noids, the return circuits of which are opened by the time delay relay.

The foregoing section of the description is concerned mainly with the automatic operation of the machine for printing, i. e., when the character selecting keys are automatically operated by the tape. Other conditions prevail when the tape selects an operation of the space bar. The space bar closes contacts in addition to those made effective by the automatic printing key. Through the connections established by both sources of control, magnet SC (Fig. 5) is energized to rock sector 238 and drive rack 239 against the adjustable space cam 243. It is already explained how cam 243 is adjusted in accordance with the number of spaces and unused line length to provide extra increments of space to stretch out a printed line until it is completely justified. Now the adjustment of the cam comes into use when rack 239 is adjusted differentially and carries member 187 along with it to move portion 188 toward the right a distance equal to the space needed between words. Following this movement, the carriage is permitted to escape toward the left, as previously described, a distance equal to the movement of the member 187 towards the right. In this way the variable spacing between words is accomplished so that automatic justification results.

Automatic indentation is accomplished in somewhat the same manner as automatic spacing. Magnet IM is energized to rock sector 248 against adjustable stop 252 and carry member 187 along therewith to position the control portion 188. There then follows the cooperation of rack 356 with portion 188 and the escapement of the carriage to the left in the same manner as described previously with respect to the variable letter spacing of carriage escapement.

When capital and upper case characters are to be selected by the automatic operation, the shift lock key is selected and along therewith there is energized a relay which sets up its own holding circuit. This relay holds a circuit through magnet SM (Fig. 4) which operates the bail 177 to shift the spacing adjustment comb 176 away from the projections w and over under the other projections W. Recording of upper case characters continues until the record tape presents a combination of perforations representing a shift release key, sensing of which combination causes deenergization of the relay and opening of the circuit through magnet SM so that the spacing comb 176 resumes the normal operating position related to the representation of lower case characters.

The carriage return key is not used at the end of each series of manual operations relating to a line, because then the carriage remains at the right as the character and control keys are operated manually to set up a line of word selections. Whenever character selections are made for a line which is short, such as the last line of a paragraph, or for any other line where justification is not wanted, the procedure is to first press the carriage return key and then the automatic print key. Depression of the carriage return key serves to set up controls for disabling the justifying controls. A relay is made effective by the carriage return key and this relay not only establishes a holding circuit, but it also opens the circuit to the magnet RM5 (Fig. 5) and the circuit between the end of bar 193 and the settable stop 201 so that the automatic adjustment of the control cam 292 does not take place after

the depression of the automatic print key for the short line of text. Since the control cam 292 is not rotated, space cam 243 remains fixed to select the normal minimum space which is selected by the rack 239 whenever a spacing operation is desired. Operation of the automatic print key, in following the operation of the carriage return key, calls into operation all the other automatic printing and spacing control functions as previously described, but with the normal minimum space between words as just mentioned.

During automatic printing of these special short and unjustified lines, when the carriage return perforations are sensed, the related key lever 53 (Fig. 4) is operated but the associated operating connections including an intermediate lever 35 are not effective. The reason for this is that the floating arm 17c is then out of alignment with the lug 12 on the carriage return lever, since it is so held by magnet CM which is then energized. However, during automatic printing, the print control key energizes relays which prepare another magnet for operation to pull down the carriage return operating lever 35 so that the carriage is returned automatically after the last character is printed or the last of a series of spacing perforations shift the carriage to close contacts to call in the auto carriage return magnet.

Upon the completion of a line of print, a series of relays are called into operation for the purpose of controlling successive restoration of the various justifying mechanisms. These relays are associated with time delay devices for staggering the closure of control contacts. One relay operates immediately to close contacts in series with the clutch magnet 335 (Fig. 5) in order to cause rotation of the control cam 292 towards the normal position. The rotation of cam 292 is continued until the projection 338 strikes against the armature lever 336 provided to stop the part in the normal position. The delayed action of the other relay is of sufficient length to allow the rotation of the cam 292 through the longest possible degree of motion which is one complete revolution. The contacts under control of the delayed action relay then open the circuit through magnet 335 so that the clutch collar 342 is thrown against stationary clutch member 347 to hold the justifying control parts in the normal position. At the same time that the relay is controlling the restoring operation of the magnet 335, it also controls the energization of magnet RM2 (Fig. 5) for pulling out the holding pawl 282 so that the space counting rack 281 may be restored to the normal position by means of spring 291.

At the end of the automatic typing operation there are called into effectiveness certain relays for closing circuits to energize the various clutch magnets RM, RM1 and RM' (Fig. 5). The clutch magnet RM1 remains energized until the circuit therethrough is open by operation of contacts when the slide 194 returns to the initial position all the way to the left. The return movement of slide 194 is also effective to operate contacts to break down the relay controls which, in turn, deenergize the clutch magnets RM and RM' to stop slides 193 and 194 in their normal positions. The opening of the circuit between the end of slide 193 and the line length stop 201 serves to deenergize magnet CS12 and the time delay control magnets. Solenoid CS12 is deenergized in time to allow free restoring movement of holder

195. In this way, the automatic justification mechanism is reset to the home position.

The foregoing section of the description is concerned mainly with the kind of operation of the machine wherein the keys are operated manually to make character selections, spacing settings and at the same time perforate a tape which, after the selection of characters for a complete line, is thereafter sensed to control the machine automatically for printing and justifying operations. There is another way of controlling the machine which is completely automatic, eliminating the need for the usual series of manual operations. The latter form of control involves the use of a prepunched tape such as the finished tape already considered which may be threaded through another form of sensing unit N as shown in Fig. 15. An important advantage residing in the use of the unit shown in Fig. 15 is the possibility of reprinting as many copies as is desired by merely running the perforated tape through a corresponding number of times. Although the control tape 52' is shown as drawn from a roll on center 128', it is contemplated that the tape could be in the form of an endless belt to repeat automatically the printing control operations. After the tape is threaded through the sensing unit, a blank sheet of paper 21 (Fig. 4) is wrapped around the platen and an adjustable sheet length control lever 380 is set to place a pair of contact rollers 381 and 382 according to the position it is desired to have a last line of print occupy on the sheet.

Turning back to Fig. 15, it is noted that the tape 52' is drawn over a guide roller 385 and between a pair of guide plates 386 and 387 before passing under a series of sensing arms 388 pivoted at 389 and provided with small rollers 390 located over an opening 391 in the plate under the tape. There are six sensing levers such as lever 388, one for each of the code perforation positions arranged across the tape. After passing to the right of the sensing levers 388, the tape flares out in a loop 135' which is built up as sensing takes place under control of the levers 388. The movement of the tape towards the right is caused by a pair of feed rollers 392 and 393 between which the tape is passed before going under levers 388.

Reference to Fig. 16 shows that supporting the lower roller 393 is a shaft 395 which extends beyond the left side frame 1261 and is supported in a standard 394. Loosely mounted near the left end of shaft 395 is a sleeve 396 carrying a pulley wheel 397 around which is wrapped the lower end of a belt 398. The upper end of belt 398 (Fig. 5) passes around a pulley 399 fastened to shaft 305 which is constantly rotating as already explained. By means of these connections, the sleeve 396 (Fig. 16) and the clutch disk 400 thereon is rotated constantly in the direction indicated. Alongside disk 400 is a clutch collar 401 which is keyed to shaft 395 but slideable thereon into and out of contact with disk 400. Engaged in a circular groove in collar 401 are the extensions of a yoke on an armature lever 402 pivoted at 403 on a bracket 404 secured to the frame 1261. Beneath the horizontally extending arm of lever 402 is a tape feed control magnet TF5, the energization of which causes the armature lever to rock in a counterclockwise direction to shift the clutch collar 401 to the left into engagement with disk 400. This action places shaft 395 and the tape feeding roller 393 thereon into connection

with the driving means so that the tape is moved under the sensing devices.

The clutch devices described would tend to feed the tape continuously but, instead, it is desired that the motion be an intermittent one with steps of equal length. Therefore, at the right end of shaft 395 (Fig. 16) is secured a ratchet wheel 405 with which an armature pawl 406 (Fig. 15) cooperates as determined by the action of a magnet TF3. Pawl 406 is pivoted on a center at 407 and normally held out of engagement with ratchet wheel 405 by a spring 408. However, whenever the clutch drive is brought into action, the magnet TF3 is also called into operation, and the pawl is rocked counterclockwise to engage the ratchet after it has moved through one tooth space of movement.

A knob 409 (Fig. 16) is attached to the extreme right end of shaft 395 so that the feed rollers 392, 393 can be operated manually to thread the tape through the sensing device independently of the automatic feeding controls. It is contemplated that similar manual feeding controls may be provided in connection with the other feeding ratchets 153, 167 and 167' (Figs. 14 and 15).

The secondary sensing devices include six sensing levers 160' (Fig. 15) and operate in the same fashion as the sensing devices described in connection with Fig. 14. They come into play after levers 388 have sensed the perforations relating to the characters of a complete line. After such a line of characters is sensed and an automatic printing indication is sensed, the feed devices including magnets TF3 and TF5 are disabled while a feeding device including a magnet TF4 is called into operation. This magnet operates a lever 163' and a pawl 166' which engages a ratchet wheel 167' on one of a pair of feed rollers 161', 162'. The rollers revolve and pull the tape 52' down past the sensing levers 160' which control the closure of one or more of six contacts 174' according to the combinations of perforations sensed. The contacts are in series with the solenoids for operating the combs controlling the selection of the character operating bars. The operation continues until the loop 135' is eliminated at which time the other feeding devices are brought into action to set up the justification factors for another line of print.

When completely automatic control is desired, a special switch is thrown into an effective position. Cooperating with the contacts of the switch is a time delay relay and another relay made effective by certain normally closed contacts of a relay operated by the automatic print key. It is through these connections that the tape feeding clutch magnet TF5 (Fig. 16) is energized. This starts the feeding of the tape 52' under the sensing levers 388, and whenever a perforation is encountered, the lever rocks in a clockwise direction to close a contact 410. These contacts 410 are in series with the comb release and shift solenoids LS1-LS6 and CS1-CS6. The combs are released in combinations which are effective to select the character or control key related to the perforated combination.

The movement of any one of the six sensing levers 388 (Fig. 15) serves to lift the common insulation bar 411 and close control contacts 412. These contacts 412 are in series with the solenoid OS (Fig. 4) which is then activated to pull down bail bar 117 and stretch springs 116 to urge depression of all character key levers 53. Because of the combinational release of only certain of the six combs (Fig. 13) only the desired key lever

53 is permitted to move downward through an operating stroke. In this way the key levers are operated successively and automatically under control of the tape with the same results in setting up justification factors as occurred when manual operation of the levers was employed in connection with the other modification of the invention.

Since magnet LM (Fig. 4) is energized directly after key lever selection and used to pull down and hold the selected key lever early in the operating cycle during automatic key selection, the same circuit is used to call feed control magnet TF3 (Fig. 15) into operation. This magnet acts to stop the feed rollers 392, 393, as already explained, with the result that the tape is held under the sensing levers 388 until the cycle of operation is completed in connection with a character selection.

The operation proceeds for sensing the character and control perforations recorded in the punched tape for an entire line, together with the setting of the justification mechanism for these characters, until at last there is sensed the combination of perforations representative of the automatic printing function. This causes actuation of the automatic print key and energization of an associated relay. The relay serves to stop the feeding of the tape under levers 388 and start the automatic typing of the line of characters corresponding to the perforations which were sensed previously for justification control only. Printing of the line of characters is controlled in the same manner as described in connection with the closure of contacts 174 (Fig. 14), the only difference being that the sensing levers now used are levers 160' (Fig. 15) and contacts 174' which are the means for making the key levers effective. The typing action continues until the automatic print key is operated while the automatic control relay is energized. If the selected line should be a short line, the automatic operation of the carriage return key will act in the same manner as during the original manual operation for that sort of line and also as previously described for the automatic typing of that line.

During the typing cycle under automatic operation, the tape 52' which has been previously sensed by levers 388, is now fed under the other sensing levers 160', due to the action of the feed rollers 161', 162' which are driven under control of magnet TF4. This magnet TF4 is wired in parallel with the feeding control magnet TF2 so that its action in feeding the tape for typing control is identical to that in effect during the partly manual operation of the machine. In the present instance, the contacts 174' are operated by sensing levers 160' to select the character printing operations. These contacts 174' are made effective at the same time as the feed control magnets TF2 and TF4, the circuit being completed through a special switch, the time delay relay, contacts 174' and the comb releasing solenoids LS1-LS6 and CS1-CS6.

A feature of the machine is the provision of devices for automatically stopping operation when a predetermined margin area is reached at the bottom of a sheet. This control is effective for either manual or complete automatic typing operation. These devices include the adjustment lever 380 (Fig. 4) and the pair of contact rollers 381 and 382 cooperating with a metallic band 415 on the platen 43. The rollers turn on a support comprising an insulation bar 416 secured to the bottom of lever 380. Cooperating

with the rollers are contact springs 417 and 418 which make up part of a circuit normally ineffective because of the insulating effect of the work sheet 21. Lever 380 is pivoted on the platen shaft 419 and adjustable to any position desired to determine the point at which the passage of the end of the sheet is to be sensed. When the end of the sheet passes under the rollers, a circuit is established between the rollers through the metallic band 415 and a magnet is called into operation for throwing the main switch of the machine to an off position to stop operation. Should the machine be operating under complete automatic control, the end of sheet control is then effective not only to disable the main switch but also to throw off the switch set to select automatic tape feeding. Printing operations may be resumed after the operator inserts a new sheet of paper and throws on the main switch along with the closure of the tape feeding switch if a completely automatic form of operation is desired.

A pair of settable contacts are provided to cooperate with the carriage so that they are closed when the end of a justified line is reached. They are used to initiate a carriage return operation during automatic tape control cycles. Referring to Fig. 4, it is seen that these contacts 583 are assembled on, but insulated from, a movable clamp 700 which is slidable on an extension 101 of the carriage track 42, but held in a selected position by a thumb screw 102. Extension 101 is marked with space graduations and the setting of the contacts is made to conform with the other line length adjustments made by the operator. A projection 703 on the movable frame of the carriage cooperates with an insulation tab on the end of one of the contact blades. The projection approaches from the right side of the contacts and closes them as an incident to the last spacing operation.

Another pair of contacts 704, Fig. 1, are associated with the carriage frame. They are also held in an adjustable insulated holder 705 and fastened to the fixed track of the carriage. These contacts are used to disable carriage return operating circuits while the carriage is at the extreme right position. They are arranged to be closed as long as the carriage is in operation. One blade of the contacts extends into the path of an insulation block 706 projecting from the left movable side frame of the carriage. When the carriage is restored to the line beginning position, the block operates to open contacts 704.

The machine is provided with interchangeable and readily removable type baskets and letter space control bars as shown in Figs. 18 and 19. It is contemplated that various sets of different book-face type styles are to be available and each basket of such type has its individual letter space control bar. Although it is possible to replace the keys 53, Fig. 4, with keys having letter space control cams *w* and *W* suited for a particular style of type, a better plan is believed to involve the use of the same keys and cams, but change the space bar or comb 176 and use a special bar which has differentially proportioned cam teeth or projections so arranged as to add to or lessen the movement usually imparted to the bar by the cams *w* and *W*.

In Fig. 18 it is seen that the type 23 are pivoted at 710 on the removable frame 711 including the semi-circular basket 712. The dot and dash line shows the line of separation between the parts held in the machine and the parts of the re-

movable basket. Frame plate 713 remains fixed and it carries a pivot wire 714 for a series of cranks 715, each of which is articulated at 716 with the operating rod 21 vibrated by the "Electromatic" cam unit under control of the related key. A restoring spring 717 is also fastened to the bottom of crank 715.

Formed on the side of each crank 715, is a tab 718 cooperating with a rounded arm 719 on the lower toggle link 26'. The operating connection between tab 718 and arm 719 is by contact only, making possible the separation of the type basket. The links 26, 26' are operated by rod 21 and crank 715 to throw the selected type-bar against platen 43 in the usual way. A pair of large thumb screws (not shown) are used to hold frames 711 and 713 together when the basket is assembled in the machine.

As a replacement for the letter space control comb or bar 176, Figs. 4 and 5, there is provided an interchangeable bar 176', Fig. 19. The bar is shaped with a pair of bayonet slots 725 and formed with an end 726 extending out of an opening 727 in the side plate 22 of the casing. Bar 176' is removed by merely pulling out to the end of the slot and then shifting it to the right and slipped over the heads of studs 182. It is carried by the usual bale made up of side arms 177, 178 and the crossbar with comb teeth 175. Attached between the outer end 726 of bar 176' and a tab on bail portion 183 is a spring 728 which pulls the bar over toward the right. The bar is stopped at a midpoint by contact between the right end of the bar with the adjustment member 187, Fig. 5.

The cam teeth 180', Fig. 19, are proportioned of different widths and varying cam faces; moreover they are located out of alignment with respect to the key cam blocks *w* and *W* wherever it is necessary to add to, or subtract from, the basic widths to provide spacing for different type styles. Since all fixed teeth 175 are evenly spaced, the cam teeth 180' are not found all evenly aligned therewith but shifted to differing extents of cam action. A plurality of such extra bars 176' are to be available for use, one for each style of type.

Figs. 17 and 17a together disclose a wiring diagram of the electrical controls as they are connected in the machine. Connection to a power source PS (Fig. 17a) is made by closure of the main switch *S*, the operation of which sends current through the main lines 450 and 451. Operation of any of the character key levers 53 (Fig. 4) causes movement of the related combs A-F (Fig. 13) and a consequent closure of a combination of the contacts 66a-66f. Referring to Fig. 17, it is seen that these contacts 66a-66f are each wired in series with a related punch control magnet PM1-PM6. An example of a punch control circuit may be traced from line 451 (Fig. 17), through wire 452, punch magnet PM1, contacts 66a, wire 453, switch MS3 closed except when operating for complete manual control, wire 454 (Fig. 17a), through normally closed contacts 455 of the punch control relay PR1 and thence through wire 456 to the other line 450. In this way one or more of the punches is operated to perforate in the tape a code representation of the character.

When any of the character keys are depressed, they lower the common bar 81 (Fig. 17a) and cause operation of contacts for various controls. One contact is closed for the purpose of energizing magnet LM which, it will be remembered, 75

operates the pointed bail bar 111 of Fig. 4 to pull down partially operated keys and lock all other keys. The circuit through magnet LM may be followed from line 451, to wire 457, wire 458, magnet LM, wire 459, contacts 83, wire 460, contacts 142 normally closed, wire 461, and wire 462 to line 450. Contacts 142 are operated by the punching mechanism, Fig. 14, to release the depressed key after tape perforation has been effected.

The operation of bail bar 81 is also effective to cause a tape feeding operation through the energization of magnet TF1 (Fig. 14), operative to rotate the feeding rollers 151, 152. Closure of contacts 85 (Fig. 17a) sets up a circuit through line 451, wire 463, magnet TF1, switch MS1 closed except for complete manual control, wire 464, contacts 85, wire 465, normally closed contacts 455, and wire 456 to line 450. This serves to advance the tape one step in readiness to receive another set of coded perforations.

The movement of any of the punches downwardly (Fig. 14) causes operation of contact lever 147 near the end of the operation and consequent opening of contacts 142. Turning to Fig. 17a, it is seen that contacts 142 are in series with the key locking control magnet LM so that, when they are opened, the keys are released to resume their normal positions. The upward movement of bar 81 opens contacts 85 to de-energize the feed control magnet TF1 and permit a spring operated restoring movement of the related armature which then acts to advance the tape.

As an incident to the usual operation of the character keys, there are times when a capital or upper case letter is desired, and a shift lock key is operated to establish a holding circuit through the shift magnet SM (Fig. 4) for shifting the justification setting comb 176 at the same time that the type basket of the machine is shifted. Referring to the top of Fig. 17, it is seen that the shift magnet SM is controlled by a shift relay SHR wired in series with contacts 466 operated by the shift lock key. This shift relay SHR is activated by a circuit passing through line 450, wire 467, contacts 466, relay SHR, wire 468, normally closed contacts 469, and wire 470 to line 451. The relay then operates to close pairs of contacts 471 and 472 to set up holding circuits for the relay and the shift magnet SM, independent of the contacts 466. The holding circuit for the relay comprises line 450, wire 467, contacts 472, relay SHR, wire 468, contacts 469 and wire 470, to line 451. The circuit held through shift magnet SM includes line 450, wire 467, contact 471, wire 473, shift magnet SM and line 451. The shift magnet is effective until the shift release key is operated to open contacts 469 and break the holding circuit through relay SHR which then allows contacts 471 to open and deenergize shift magnet SM.

As the punching control operations are taking place, other connections are effective for establishing justification settings according to the widths of the characters operated. As any key lever 53 is depressed (Fig. 5), the justification comb 176 is shifted to the right and carries along therewith the member 187 with the clutch projection 196 (Fig. 6a), having a normal frictional connection with the slides 193 and 194 as already explained. It is desired that this frictional clutch connection be maintained until the type width setting has been established and then the connection is to be broken with respect to projection

196 and the slides 193 and 194 are to be locked in the adjusted position. Solenoids CS7 and CS8 are provided for the purpose of locking the slides in adjusted position, and they are energized for this purpose near the end of the key depression movement. At the end of the downward stroke of any of the character keys, the common bail 81 (Fig. 17a) strikes the adjustable ends of cranks 90 and 91 to close contacts 88 and 89. The circuits through contacts 88 and 89 are directed through a relay PR2 which not only sets up a holding circuit for itself but also calls into operation the solenoids CS7 and CS8 to lock the justification setting slides. The circuit through relay PR2 may be traced from line 451, through wires 457, 458, wire 474, contacts 88, wire 475, relay PR2, wire 476, contacts 89, wire 477, wire 465, contacts 455 and wire 456 to line 450. The energized relay PR2 then shifts a pair of contacts 478 and 479 to close holding circuits and operate circuits for the solenoids. The solenoid operating circuit shunts contacts 88 and 89 by coming from line 451, Fig. 17, through wire 491, solenoid CS7 and a parallel circuit through wires 483, 484, contacts 263 and the other solenoid CS8, then in common through wire 481, Fig. 17a, contacts 479, wire 477, wire 465, contacts 455, wire 456 and line 450. The holding circuit for relay PR2 includes line 451, wires 457, 458, 474, contacts 88, wire 475, relay PR2, wire 476, contacts 89, wires 477, 465, contacts 455 and wire 456 to line 450. Contacts 89 are opened before contacts 88 which are the first to close.

Upon release of a character key lever 53 (Fig. 17a) the upward movement of bail 81 and the adjustment of crank 90 permits contacts 88 to remain closed until near the end of the upward stroke. This serves to hold the relay energized throughout the operating cycle. Repetition of this cycle of operation results in the accumulation of the widths of the various characters recorded, by the successive movements of the slides 193, 194, 195 into a setting position. Operation of the control keys does not cause movement of the slides because they do not affect the comb 176.

Operation of the space bar S (Fig. 17) causes the closure of contacts 262, 262' and the opening of contacts 263 for effecting restoration of the slides 194, 195. When the space bar is operated, solenoid CS1 is energized by the closure of contacts 262' in order that slide 193 may be locked to the frame to hold its advanced position while the other slides 194 and 195 are restored. The other solenoid CS8 is deenergized by the opening of contacts 263 in series therewith for the purpose of freeing the slide 194, so that it may be restored by a positive movement against the frictional contact between slide 194 and projection 196. The circuit through solenoid CS7 includes line 451, wire 491, solenoid CS7, wire 482, wire 481, Fig. 17a, contacts 479 (closed by relay PR2 when it is energized by the closure of contacts 88 and 89 when bar 81 is lowered by the space key) wires 477, 465, contacts 455, and wire 456 to line 450. Immediately upon the shifting of slides 194 and 195, a series of control contacts 494, 497, 500, 501, 502 and 503 are closed. The various controls exercised by these contacts are explained as this disclosure continues.

Whenever the space key is operated, it is desired that solenoid CS7 become active to lock slide 193 in the adjusted position, while the other solenoid CS8 is supposed to remain inactive in order that slide 194 may be restored to the normal position. For this purpose, solenoid CS7 is

connected to a normally open contact 262' while the other solenoid CS8 is connected to a normally closed contact 263, the condition of said contacts 262' and 263 being reversed by the operation of the space bar. When the space bar is operated, solenoid CS7 is made effective through the circuit already described, because at this time relay PR2 is again effective to close contacts 479 (Fig. 17a) because the space bar is also effective to operate bail 81 to close contacts 88 and 89 in the same way that the character keys operate. However, the circuit is not carried through the other solenoid CS8 (Fig. 17) because contacts 263 are opened by the space bar.

Resetting magnet RM' is made effective to pull slide 194 back to the normal position every time the space bar is operated. The circuit through magnet RM' may be traced from line 451 (Fig. 17) through wires 505, 506, magnet RM', contacts 495, contacts 494, wire 493, contacts 262', wires 492, 482, 481 (Fig. 17a), contacts 479, wire 477, wire 465, contacts 455 and wire 456 to line 450. The completion of the movement of slide 194 towards the left (Fig. 17) causes the opening of contacts 494 and deenergization of magnet RM'.

Operation of the space bar also causes activity of the reset magnet RM1 for moving the other slide or holder 195 back to the normal position. A circuit for this magnet may be followed through line 451, wire 507, magnet RM1, wire 508, contacts 509 normally closed, wire 510, contacts 503, wire 493, contacts 262', wires 492, 482, 481 (Fig. 17a), contacts 479, wires 477 and 465, contacts 455 and wire 456 to line 450. The completion of the movement of holder 195 towards the left under control of magnet RM1 causes the opening of contacts 503 and resulting deenergization of the same magnet.

Operation of the space bar also causes energization of the space control magnet SC1 for operating the space counting devices. The circuit through magnet SC1 comprises line 451, Fig. 17, wire 511, magnet SC1, wire 493, space contacts 262', wires 492, 482 and 481, from which point on, the circuit is the same as those already described.

Operation of the indent key (Fig. 17) closes contacts 527 to energize the magnet IM which is used as explained hereinbefore to shift the spacing mechanism for the first lines of paragraphs and for short lines. The circuit through magnet IM includes line 451, wire 491, wire 528, magnet IM, contacts 527, and wire 528 to line 450.

The movement of the pointer 211 (Fig. 11) towards the right is watched by the operator when it is approaching the end of the space allotted for the printed line. Before it reaches this limit, the operator stops at the end of a complete word, or hyphenates the word, and then depresses the space bar to restore various parts as already explained, and following this, operates the auto print key. The auto print key calls into operation many of the justification controls before the character keys are automatically operated.

Depression of the auto print-key (Fig. 17a) causes the closure of contacts 513 and 514 and the energization of an auto print relay APR to adjust many contacts for controlling the justifying and printing operation. The circuit through relay APR may be followed through line 450, wire 462, contacts 514, wires 515, 516, relay APR, relay magnet BM, wire 517 (Fig. 17), normally closed contacts 518, wires 519, 520, 521 to line 451. The relay then prepares a holding circuit for itself by the closure of contacts 523. The

holding circuit includes line 450 (Fig. 17a), wire 456, wire 522, contacts 523, relays APR and BM, wire 517, Fig. 17, contacts 518, and wires 519, 520, 521, to line 451. The relay also sets up a circuit for another control relay PR1 due to the closure of contacts 524. The circuit through relay PR1 may be traced from line 451 (Fig. 17a), through wire 480, relay PR1, wire 525, contacts 524, wires 522 and 456 to line 450. Closure of contacts 536 by relay PR1 calls into operation the resetting magnet RM5 (Fig. 5) which then operates to draw slide 193 toward the right until a contact is established between the metallic strip 192 of the bar on the end of the slide and the terminal point 200' on the justification line length setting arm 201. The circuit through resetting magnet RM5 includes line 451 (Fig. 17), wire 530, normally closed contacts 531, magnet RM5, wire 532 (Fig. 17a), normally closed contacts 84, wire 533 (Fig. 17), normally closed contacts 534, wire 535 (Fig. 17a), contacts 536 and wire 456 to line 450. When the slide 193 reaches the limit of line length set by the operator, the resetting magnet RM5 is deenergized by the opening of contacts 531 (Fig. 17), due to the energization of the associated relay R3 set into operation by a circuit through slide 193 and the adjustable contact stop. A delay timing relay DR1 is also called into operation by the arrival of the justification setting slide 193 in position at the end of the line. Relays R3 and DR1 are connected in parallel with a wire 537 extending to the contact point 200' on the adjustable stop. The relays are connected to the main line 451 by wires 538 and 539, respectively. The circuit continues from the contact point 200', through the strip 192 of slide 193 and over to the contact member 190' and then to wire 540, wire 532 (Fig. 17a), contacts 84, wire 533 (Fig. 17), contacts 534, wire 535 (Fig. 17a), contacts 536 and wire 456 to line 450.

Relay R3 operates to close contacts 541 for energizing the magnet 334 to release the justification setting cam 292 (Fig. 5), so that it may rotate a selected extent to set up the justification factor. The circuit through magnet 334 (Fig. 17) includes line 451, wire 542, magnet 334, wire 543, normally closed contacts 544, contacts 541, wire 537, terminal 200', slide 193 and then over to the other side of line through connections already traced. It is noted that the magnet 334 is deenergized soon after it is energized, due to the opening of contacts 544 by delay relay DR1. Although both relays R3 and DR1 are energized at the same time, contacts 541 close shortly before contacts 544 open, due to the adjustment of the contact operating armature 545 held in a normally retracted position against an adjustable screw 546. The result is that immediately after the justification setting cam 292 is released by operation of stop crank 336, the crank is again dropped into the stopping position to hold the cam when it returns to the normal position.

Relay R3 (Fig. 17) operates to close other contacts 547 to call into operation, magnet 335 (Fig. 5) for operating the clutch to drive the justification cam 292 into the position determined by the setting of the extension 224, set according to the number of word spaces and unused line length. The circuit through magnet 335 (Fig. 17) may be traced from line 451, through wire 542, magnet 335, wire 548, normally closed contacts 549, contacts 547, wire 537, terminal 200', slide 193 and over to the left side of the line through the connections already mentioned.

It will be noted that contacts 549 are operated, 75

after a short delay, to deenergize magnet 335 in the same fashion that magnet 334 is deenergized by the opening of contacts 544. However, the length of time that magnet 335 is held in operation is sufficient for the setting cam 292 to go through a little less than a complete revolution which is necessary for a setting in some instances. After the cam arrives in a position where it is jammed against the extension 224, the driving clutch will slip during the short time that magnet 335 maintains the clutch connection.

As the settable cam 292 (Fig. 5) rotates a differential amount, it carries with it the space control cam 243 which is then set to determine the length of the spacing between words during the subsequent automatic printing operations. The cams 292 and 243 are held in the adjusted position because clutch roller 342 comes into engagement with the stationary clutch surface 347 when magnet 335 is deenergized directly after the setting of cam 292.

The closure of contacts 514 (Fig. 17a) by the automatic print key calls into operation the tape feeding magnet TF2 which operates feed rollers 161 and 162 (Fig. 14) to drive the tape downward so that the first line of perforations are under the sensing levers 160, so that they can close contacts 174 and call into operation the selected character printing lever. The circuit through magnet TF2 (Fig. 17a) may be followed from line 450, through wire 462, contacts 514, wire 515, switch MS2, magnet TF2, wire 550, wire 551, contacts 107, wire 458, and wire 457 to line 451.

Although a circuit is prepared through contacts 523 to hold the energization of the feed magnet TF2, it is disabled soon after energization because contacts 107 are opened as soon as any of the keys are automatically operated.

When the tape is advanced, it is sensed and contacts 174 (Fig. 14) are closed in combinations according to the number of sensing devices falling into the code openings. The closure of contacts 174 is effected to call into operation the pairs of solenoids LS1-LS6 and CS1-CS6 (Fig. 13). Turning to Fig. 13, it is noted that the combs controlled by the solenoids are normally unlocked but are held by latches 4 whenever the control magnet BM is energized. It will be remembered that the blocking magnet BM is energized early in the automatic printing cycle when the relay APR (Fig. 17a) is energized in series therewith. The operation of this magnet BM results in the locking of all six combs A-F by latches 4. It is the purpose of the solenoids to release selected combs and pull them to the left in position to allow the depression of a certain character printing key. An example of a circuit through one related pair of the solenoids may be followed from line 451 (Fig. 17a) through wires 457 and 458, contacts 107, wire 551, solenoids LS1 and CS1, contacts 174, wire 552, normally closed contacts 553, wires 515 and 516, contacts 523, wire 522 and wire 456 to line 450. The fast acting solenoid LS1 (Fig. 13) is the first to operate to unlatch comb A and then the other solenoid CS1 comes into operation to pull the comb to the left to set up key selecting comb openings under the levers 53 in combination with other operated combs.

Upon operation of the auto print key and before the selected key levers are pulled down, the conditioning magnet CM' (Fig. 4) is deenergized to allow the print enabling arms 70 to rest underneath the lugs 72 so that operation of the key levers 53 can be effective to cause printing opera-

tion. The carriage return preventing magnet CM is energized by a circuit set up through the automatic print contacts to make ineffective the single arm 75c. The circuit follows a path through line 450 (Fig. 17a), wire 462, contacts 514, wires 515 and 516, magnet CM and wires 458 and 457 to line 451. The circuit through the conditioning magnet CM is held throughout the automatic printing cycle by means of the closure of contacts 523 as a shunt circuit around the contacts 514 which are opened when the automatic printing key is released. Magnet CM then opens contacts 554' which are in series with magnet CM' which is normally energized through the following circuit: Line 450, wire 722, magnet CM', switch MS4, contacts 554', wires 458, 457 and line 451.

Early in the automatic printing cycle, the solenoid OS (Fig. 4) is energized to pull down the springs 116 and a key lever 53 for printing operation. For this purpose the relay R1 (Fig. 17a) is energized and held in operation to make the solenoid active. The relay R1 is first energized by means of a circuit including line 450, wire 462, contacts 514, wires 515 and 516, relay R1, wire 555 (Fig. 17), contacts 556 and wires 520 and 521 to line 451. The operation of relay R1 closes the associated contacts 557 (Fig. 17a) and the auto print relay closes other contacts 558 to set up a holding circuit through the relay and the associated solenoid OS. The holding circuit includes the following connections: Line 450 (Fig. 17a), wires 456 and 522, contacts 523, wire 516, and contacts 557 after which the circuit branches out in two parallel connections, the one being through relay R1 and wire 555 as already described and the other passing through wire 559, contacts 558 closed by relay APR, wire 560, solenoid OS and wire 555 (Fig. 17) and then through the common connections including contacts 556 and wires 520 and 521 to line 451.

Automatic operation of any of the key levers causes depression of bar 81 (Fig. 9) and operation of switch lever 99 with a delayed snap action at the end of each printing cycle. Actuation of the switch serves to open contacts 107 (Fig. 17a) to disable the control circuits passing therethrough, and at the same time the other contacts 104 and 106 are closed.

Closure of contacts 104 sets up a carriage escapement control by energization of escapement clutch magnet CE (Fig. 4) to release clutch 350 and engage the carriage with rack 356 through clutch 353. In Fig. 17 it is seen that clutch magnet CE is energized by a circuit through line 451, wires 521, 520, magnet CE, wire 565, contacts 566, wire 567 (Fig. 17a), contacts 104, wire 559, contacts 557, wire 516, contacts 523, wires 522 and 456 to line 450. This operation will serve to clutch the carriage to gear 355 and then declutch it from the carriage frame. The first part of the movement of armature 361 (Fig. 4) operated by magnet CE, serves to close contacts 375 to energize clutch solenoids CS13 (Fig. 5) to lock the escapement setting member 187 in the adjusted position. The circuit for solenoid CS13 is shown in Fig. 17 and includes line 450, wire 568, contacts 375, wire 569, solenoid CS13 and line 451. The solenoid acts instantly as a magnetic clutch to hold member 187 where it is set to the exact width required by the character printed, and the carriage will move accordingly toward the left to assume the required position.

At the same time that carriage escapement magnet CE is energized, a time delay relay DR5

is also brought into action to restore the parts held operative through the normally closed contacts 556 and 566 (Fig. 17). The circuit through relay DR5 follows a path from line 451 (Fig. 17a), through wires 457, 458, contacts 106, wire 570 (Fig. 17), relay DR5, wire 567 (Fig. 17a), contacts 104, wire 559, contacts 557, wire 516, contacts 523, and wires 522, 456 to line 450. The holding circuit for relay DR5 is established through a pair of contacts 571 operated by the armature which has an adjustable starting position to vary the time of operation. The holding circuit includes line 450 (Fig. 17), wire 572, contacts 571, wire 567, relay DR5, wire 570 (Fig. 17a), contacts 106, wires 458 and 457 to line 451.

Escapement clutch magnet CE when deenergized by the opening of contacts 566 (Fig. 17) will in turn allow the opening of contacts 375 to deenergize solenoid CS13, so that it releases member 187. The carriage movement controls are restored by spring 351 (Fig. 5) and magnet CE (Fig. 4) is deenergized when the spring pulls the stop member 358 (Fig. 5) back against a fixed block 359. Member 187 is also restored as soon as solenoid CS13 is deenergized.

The time delay relay DR5 will remain energized through its holding circuit until the contacts 106 (Fig. 17a) are opened by the return action of switch 99 due to the restoration of the operated character key. The keys are released to be restored by deenergization of solenoid OS (Fig. 17a), the return circuit of which is opened by the contacts 556 of the operated delay relay DR5. The combs A-F are restored directly after the keys are allowed to move upward, because the associated solenoids LS1 and CS1 are deenergized at the proper time by the opening of contacts 107, so that springs 68 may push the combs toward the right (Fig. 13).

The foregoing sequence of operations completes the automatic typing of a character. Other controls are called into operation when automatic spacing or other spacing control is selected by the tape.

When the space bar S (Fig. 17) is operated, contacts 262 are closed and a circuit is set up through the space control magnet SC. The circuit follows a path from line 451 (Fig. 17) through the wire 491, wire 526, magnet SC, contacts 262, wire 574 (Fig. 17a), contacts 575 closed during automatic printing, wire 516, contacts 523 and wires 522 and 456 to line 450. Magnet SC (Fig. 5) then operates to shift rack 239 and the connected member 187 over against space cam 55243 which has been adjusted for the proper expansion of spacing between words. Following the movement of member 187, the carriage will escape due to the energization of magnet CE (Fig. 4) which is called into operation automatically for word spacing controls in the same way that it is brought into play for character spacing control.

When the code perforations for the indenting operation are sensed on the tape, the indent key 65 (Fig. 17) is pulled down to close contacts 527. There results the energization of indent magnet IM and the movement of rack 247 (Fig. 5) and the connected member 187 towards the right into the adjusted position. The escapement of the carriage follows directly thereafter just as in character and space control escapement.

The sensing of code perforations relating to the shift lock key calls it into operation for not only providing the usual type basket movement 70 of the "Electromatic" but it also serves to oper-

ate magnet SM (Fig. 4) for shifting the variable escapement comb 176 under the spacing control wedges W for securing proper escapement movement. The circuit through magnet SM (Fig. 17) is set up by the automatic closure of contacts 466 and the energization of relay SHR as explained in connection with manual operation. Upper case printing and spacing continues until perforations are sensed relating to the shift release operation. Automatic operation of the shift release key, opens contacts 469 to disable the shift magnet SM and allow the parts to resume the normal position relating to lower case operations.

The carriage return operation is made independent of key operation during automatic printing. The closure of the settable line length contacts 583, Fig. 4, at the end of each line when combined with the depression of the automatic print key causes an automatic carriage return operation without code perforations relating to such operation.

When setting up the last line of the paragraph manually, or any line which is short and where justification is not desired, the special justification spacing controls are disabled by first pressing the carriage return key and then operating the automatic print key. During the recording of such short lines, the manual operation of the carriage return key energizes relay R4 (Fig. 17) through the contacts of relay PR1 (Fig. 17a) and contacts 576 (Fig. 17) operated by the carriage return key. Relay R4 then operates to disable the circuit from the justifying reset magnet RM5 which usually operates to pull slide 193 (Fig. 5) over towards the right to take up the unused space in the ordinary full length line. The circuit through control relay R4 may be followed from line 450 (Fig. 17a) through wire 456, contacts 455, wire 454 (Fig. 17), carriage return contacts 576, wire 577, relay R4, wire 578, contacts 579 and wires 520, 521 to line 451. Relay R4 then opens contacts 534 to disable the circuit usually allowed to pass through reset magnet RM5 and slide 193 so that the automatic adjustment of the justification cams does not result during this operation. Since the variable space cam 243 (Fig. 5) is not adjusted, the normal minimum width of spacing is selected between words when the short line is printed.

Relay R4 sets up a holding circuit for itself by the closure of contacts 643. The circuit involves line 450, wire 645, contacts 643, relay R4, wire 578, contacts 579, wires 520 and 521 to line 451.

Another connection effected by relay R4 is the one involving contacts 644 which are closed during automatic typing. And late in the cycle, when the auto print key is automatically depressed, a circuit is set up for relay R5 through contacts 644 to cause a carriage return operation by operating magnet R6. The circuit through relay R5 includes line 450, Fig. 17a, wire 580, contacts 513, wire 581, Fig. 17, wire 582, contacts 644, wire 584, wire 585, relay R5, wire 570, Fig. 17a, contacts 106, wires 458, 457 and line 451. Closure of contacts 587 then operates magnet R6 to pull down the carriage return bar 35'.

Contacts 583, Fig. 17, are in parallel with contacts 644 and serve to energize relay R5 to cause carriage return operations at the end of full length lines after automatic typing when the auto print key is pulled down automatically.

Contacts 704, Fig. 17, are in series with magnet R6 to disable it and prevent carriage return op-

eration as long as the carriage is in the extreme right position.

When the automatic print key is manually operated following the manual operation of the carriage return key for a short line, the automatic typing of the line begins as previously described with the normal minimum space selected between words as already mentioned.

During the automatic printing of a short line, automatic operation of the carriage return key does not cause operation of the carriage because at the time the adjustable link 75c (Fig. 4) has been pulled out of cooperation with the lug 72 on the carriage return lever 53 by the operation of magnet CM which is effective during automatic printing as already explained.

The carriage return operation is called into effect by other automatic means whenever the end of a printed line is reached during the automatic control cycle. The relay R5 is provided to determine such operation under a conjoint control of the contacts 583 operated by movement of the carriage and other contacts operated by the auto print key. This relay R5 then calls into operation the magnet R6 for pulling down the carriage return operating bar 35' to get the desired control. The circuit through relay R5 may be traced through the contacts of relay R4 as follows: Starting at line 450 (Fig. 17a) current passes through wire 580, contacts 513, wire 581 (Fig. 17), wire 582, contacts 583 closed by the carriage at the end of a line, wire 584, wire 585, relay R5, wire 570 (Fig. 17a), contacts 106 closed after the last letter is printed, and wires 458 and 457 to line 451.

Relay R5 (Fig. 17) then closes associated contacts 587 to make magnet R6 effective by means of the circuit from line 450 (Fig. 17a), wire 462, contacts 514, wire 516, wire 516, relay APR, magnet BM, wire 517 (Fig. 17), relay R6, contacts 704, wire 586, contacts 587, relay R5, wire 570 (Fig. 17a), contacts 106 and wires 458 and 457 to line 451. The magnet R6 then acts directly on the carriage return bar 35' (Fig. 17) to pull it down and cause the usual "Electromatic" carriage return operation.

Near the end of the automatic printing operation, when relay R5 is operated, other relays DR2 and DR3 are energized through contacts 55 closed by relay R5. Relay DR2 is quick acting while actuation of relay DR3 is delayed because it is a slow acting magnet. The circuit through relays DR2 and DR3 is composed as follows: Line 451 (Fig. 17), wire 521, at which point the circuit branches out in one direction through contacts 588, and relay DR2 and also through the other relay DR3 and wire 589, and then together through wires 590, 591, contacts 592, wire 593, to the other line 450. Relay DR2 establishes a holding circuit comprising line 451, wire 521, contacts 588, relay DR2, wires 590, 591, contacts 595, wire 596, wire 528 to line 450. Relay DR2 also closes other contacts 597 to set up a circuit to the clutch magnet 335 determining the restoration of the justification control cam. The circuit through magnet 335 may be traced through line 450, wire 528, wire 596, contacts 597, wires 598 and 548, magnet 335, wire 542 to line 451. Magnet 335 (Fig. 5) then closes driving connections to turn cam 292 until it strikes the crank 336 when reaching the home position.

The space count restoring magnet RM2 is operated through the connections mentioned to pull away the holding latch 282 (Fig. 5) and allow restoration of rack 281. The circuit for magnet

RM2 (Fig. 17) may be followed from line 451, through magnet RM2, wire 591, contacts 595, and wires 596 and 528 to line 450.

The delay in the action of relay DR3 is of sufficient duration to permit the restoring operations initiated by magnets 335 and RM2 before the relay acts to open the contacts 588 to break the circuit through relay DR2 and deenergize the restoring magnets. An armature 599 is associated with relay DR3 and held in an adjusted position to cause operation of contacts 588 at the proper time.

The energization of relay R5 also serves to initiate restoration of the justification members through the energization of relay R1 by the closure of contacts 600 in series therewith. The circuit includes line 450 (Fig. 17), wire 593, contacts 600, wires 585, 584, relay R1, contacts 497, and wires 496 and 505 to line 451. Relay R1 then sets up its own holding circuit by closure of contacts 602. The holding circuit is made up of line 450, wire 603, contacts 602, wire 498, relay R1, contacts 497, wires 496 and 505 to line 451. The relay also closes connections to energize the restoring clutch magnets RM, RM1 and RM'.

The circuit through restoring magnet RM may be traced through line 451, wire 505, magnet RM, contacts 605, contacts 602, wire 603 to line 450. The other restoring magnet RM1 is energized through line 451, wire 507, magnet RM1, wire 508, contacts 606, wire 607, contacts 501, wire 608, wire 584, wire 498, contacts 602, wire 603, to line 450. The other magnet RM' is energized by the circuit from line 451, wire 505, wire 506, magnet RM', contacts 609, wire 610, wire 498, contacts 602, and wire 603 to line 450.

The restoring magnet RM1 is deenergized as soon as slide 195 reaches the home position because it then opens contacts 501 in series with the restoring magnet. The return of slide 194 due to the restoring control of magnet RM' also serves to break the restoring circuits by the opening of contacts 497 which act to deenergize relay R1 so that it opens contacts 602, 606 and 609 associated therewith to break the circuits through restoring magnets RM and RM'.

As magnet RM restores slide 193, the circuit through 193, contact 192, and adjustable terminal 200' (Fig. 17) is opened and magnet CS12 and relays R5 and DR1 are deenergized. In this way the automatic justification mechanism is reset to the normal condition.

Operations are continued when the tape feed magnet TF2 is reenergized by the closure of contacts 107 (Fig. 17a) to advance the tape to a new perforation sensing position, thereby initiating another printing cycle.

The foregoing sections of the circuit description are concerned mainly with the use of the machine as operated with alternate manual setting selections and automatic printing operation. Another form of control is provided for use with the completely automatic unit N (Fig. 15). In this modification, the tape not only controls printing but it also controls initial operation of the keys for making the justification settings.

The leading edge of the tape 52' (Fig. 15) is threaded through the rollers 392, 393 and drawn down through rollers 161' and 162', and the first set of code perforations is brought near the sensing levers 388 so no time is lost in beginning the sensing operations for the justification settings. A blank sheet of paper is then placed around the platen of the machine and the adjustable sheet length arm 380 (Fig. 4) is adjusted to the desired 75

position to terminate operation when the end of the sheet is reached. Following this, the automatic control switch AS (Fig. 17a) is drawn to the left to operate associated contacts for complete automatic control. The closure of switch AS operates a contact 611 which brings a delay relay DR4 into operation by a circuit including line 451, wire 612, relay DR4, wire 613, magnet AM, wire 620, 621, contacts 611, wire 614, normally closed contacts 615, wires 616, 456 to line 450. Relay DR4 then acts to close contacts 617 for a tape feeding control circuit through clutch magnet TF5. The feeding control circuit includes line 451, wire 618, magnet TF5, wire 619, contacts 617, wires 620, 621, contacts 611, wire 614, contacts 615, wires 616, 456 and line 450. Magnet TF5 (Fig. 16) then operates to close clutch 401 and advance the tape 52' (Fig. 15) under the sensing levers 388, so that the levers can be dropped into any of the perforated code positions. As the tape is advanced, a loop 135' is formed in readiness for automatic print operation in the same manner as explained in connection with the unit M (Fig. 14).

It is noted that along with the energization of relay DR4, a magnet AM is made operative. This magnet cooperates with the lever 6 of bar 10 (Fig. 13) to release the latches 4 so that they cooperate with the combs A-F in readiness for an automatic comb selecting operation. When the sensing levers 388 (Fig. 15) sense perforations, they close related contacts 410 (Fig. 17a) in series with the comb controlling solenoids LS1-6 and CS1-6.

During automatic operation, the contacts 410 are closed in various combinations to operate the pairs of solenoids CS1-6 and LS1-6. The circuits through the solenoids are as follows: Line 451 (Fig. 17a), wires 457, 458, contacts 107, wire 551, solenoids CS1, LS1, contacts 410, wire 634, contacts 611, wire 614, contacts 615, wires 616 and 456 to the line 450. Operation of these solenoids in combination, cause movement of selected combs toward the left (Fig. 13) and provide an open path for the automatic depression of one of the key levers 53. Operation of any one of the six levers 388 (Fig. 15) serves also to close contacts 412 (Fig. 17a) to set up connections for operating solenoid OS. The circuit through solenoid OS may be traced through line 451 (Fig. 17), wire 521, wire 520, contacts 556, wire 555, Fig. 17a, solenoid OS, wire 560, contacts 624, wire 623, contacts 412, wires 622, 619, contacts 617, wires 620, 621, contacts 611, wire 614, contacts 615, and wires 616 and 456 to line 450.

Solenoid OS (Fig. 14) then acts to pull down all springs 116 and operate the selected lever 53, because the setting of the combs permits only one lever to be depressed. The operated key then provides a justification setting by shifting the comb 176 (Fig. 5) and setting parts 193, 194, 187 as explained before with relation to manual operation of the keys for the justification setting.

Closure of contacts 83 (Fig. 17a) by the depressed key serves to operate magnet LM to pull down the operated key and lock out all others. Part of the same circuit is used to energize the feed control magnet TF3 through the circuit, line 451, wire 618, magnet TF3, wire 626, contacts 627, wire 628, contacts 83, wire 460, contacts 142, and wires 461, 462, to line 450. The operated magnet TF3 (Fig. 15) then moves pawl 406 to hold the feed rollers 392, 393 after they have advanced the tape through one step of movement.

The sensing operation continues to select the

characters and control operations recorded in the tape for a given line, together with the setting of the justification factors connected with the line until the perforated combination is sensed relating to the automatic print key. Operation of this special key serves to energize the related relay APR (Fig. 17a) in the usual way. The relay then opens contacts 624 to interrupt the connections for delay relay DR4, thus breaking the connections previously established by the relay DR4 and stopping the feeding of the tape under sensing levers 388 (Fig. 4). Other connections are established to cause operation of magnet TF4 to draw the tape in the loop 135', past the sensing levers 160' to control the printing of the line for which the justification setting has been established. The printing of the line continues in the same manner as previously described for automatic typing, the action ceasing when the automatic print key is operated automatically while the relay APR is energized. If the typed line is a short line, the automatic operation of the carriage return key, will act in the same manner as during the manual operation for the line, and during typing it is also controlled as previously described for the automatic typing of such a line.

During the printing cycle of the automatic operation, the tape is drawn under the sensing levers 160' by the operation of magnet TF4. This magnet is wired in parallel with the other feed control magnet TF2, and the feeding operation is identical to that produced during the automatic printing control exercised by the unit M in Fig. 14.

Sensing levers 160' control the operation of the comb selecting solenoids LS1-6 and CS1-6 by the closure of contacts 174' in various combinations. The circuit through one example of such connections can be followed in Fig. 17a, starting with line 451 and passing through wire 457, wire 458, contacts 107, wire 551, solenoids CS1, LS1, contacts 174', wire 630, contacts 631, wire 632, contacts 633, wires 515, 516, contacts 523 and wires 522, 456 to line 450.

A feature of the machine is the provision of devices for stopping operation when the lines of print approach within a predetermined distance from the bottom of the work sheet. The control is effective in connection with the use of either control units M or N, though it is more useful with the completely automatic unit of Fig. 15. The size of the bottom margin is selected by the position of lever 380 (Fig. 4) which positions sensing rollers 381 and 382, so that the circuit is established through a metallic band 415 which comes into contact with both rollers when the end of the sheet passes. Referring to Fig. 17a, it is seen that the circuit passing through the rollers includes a switch operating relay SR1 for operating the main switch S to the off position. The circuit includes line 450, wire 635, switch SW1, roller 382, band 415, roller 381, wire 636, wire 637, magnet SR1, wire 457, to line 451.

During complete automatic control, another switch operating magnet SR2 is energized to disable the connections through switch AS whenever the end of the paper is sensed. The circuit for operating the automatic switch is connected in parallel with the control magnet SR1 and includes line 451, wire 640, magnet SR2, wire 637, contact roller 381, band 415, roller 382, switch SW1, wire 635 and line 450.

The stopping control magnets SR1 and SR2 are connected in series with other contacts 641 and 642 provided to call them into operation.

whenever the tape is exhausted in one of the automatic control units. The contacts 641 and 642 are normally open and held so by the position of card levers cooperating with the web tape 52 (Fig. 14) and 52' (Fig. 15). The levers are arranged to operate when the tape is exhausted and permit closure of contacts to call the switch operating magnets into action to stop the machine whenever the tape runs out. Switches are in series with the contacts 641 and 642 to disable the locking control whenever desired.

A pair of relays R2 and R2', Fig. 17a, are provided to insure that an actuated key lever is not released to return to its normal position until after the resetting of slide 194. Magnet LM, which is provided to hold down the operated keys, is maintained in an energized condition by a circuit through the contacts 651 operated by relay R2. Relay R2 is energized by a branch circuit activated at the same time that the magnet LM is energized. The circuit through relay R2 includes line 450, wire 462, wire 461, contacts 142, wire 460, contacts 83, wire 459, relay R2, wire 652, normally closed contacts 653, wires 654, 458 and 457 to line 451. The relay then closes contacts 651 to provide a shunt path for magnet LM and it also closes contacts 655 to call into operation the secondary delay relay R2'. Relay R2' then attracts an adjustably retracted armature 656, the end of which finally strikes one blade of contacts 653 and opens them to release both relays and permit contacts 651 to open. However, by this time, slide 194 has been restored, and magnet LM has served the purpose of holding the character key operated long enough. The depressed key is released when magnet LM is deenergized.

When the control tapes are not used, i. e., for a completely manual style of operation, the justification controls are maintained, but all sensing and auto printing controls are disabled by operation of switches. In Fig. 17a it is seen that switches MS1 and MS2 can be opened to disable tape feeding. In the same figure it is noted that a switch MS4 is in series with the key interposer control magnet CM'. This last mentioned switch is opened for the second portion of alternate justification and printing by manual control, because it is then desired that the interposers 70, Fig. 4, be in effective positions under key levers 53. Another switch MS3, Fig. 17, is opened to prevent punch operation during complete manual control.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In an automatic printing machine with a set of control keys and printing mechanism operated thereby, the combination of a first program device including a tape perforating mechanism operated under control of said keys by a preliminary operation thereof, means under control of said tape for operating said keys for a secondary operation to operate said printing mechanism, a second program device having a prepared tape for operating said keys to operate said printing mechanism, and means cooperating with the keys and both program devices for

selectively choosing one of three styles of operation, manual operation of the keys for printing control, printer operation under control of the keys as controlled by the tape of said first program device, or printer operation under control of the keys as controlled by the tape of said second program device.

2. The invention set forth in claim 1, including a movable record sheet carriage, escapement mechanism therefor, and justification control devices cooperating with said escapement mechanism and adjusted by a preliminary operation of said keys either manually or under control of the tape of said second program device.

3. In a printing machine having a set of printing members for recording on a work sheet, operating mechanism for said members, control keys for said operating mechanism, a carriage adapted to hold said work sheet, an escapement mechanism for said carriage, the combination of a justification control mechanism operated by said keys as a preliminary to the control of printing, said justification control mechanism later cooperating with said escapement mechanism to control word spacing while printing takes place, means for preventing operation of said operating mechanism during the first operation of the control keys to set up the justification mechanism, whereby no printing is effected, means under control of the justification control mechanism for disabling the preventing means and to allow the operation of the control keys to effect printing upon a second operation of the keys, a carriage return key, and means under control of said return key for disabling the word spacing operation of said justification control mechanism, whereby printing can be effected without justification.

4. In a typing machine having a space key, a set of character selecting keys and a printing mechanism operated thereby, a carriage, and an escapement mechanism operating with said carriage, the combination of a justifying mechanism including a pair of connected face cams having spiral formations, means between said escapement mechanism and one of said cams for determining justified word spacing, means for setting a predetermined length of line, a stop for the second cam, said stop being moved obliquely across the face of said cam under control of a pair of positioning means, one of said positioning means being operated under control of said space key, and the other of said positioning means being operated under control of said line length setting means and the justification mechanism according to the unused length of line determined by preliminary operation, and means for rotating said cams to bring the second mentioned cam into contact with said stop.

5. In an automatic typing machine with a set of control keys and printing mechanism operated thereby, the combination of means for causing automatic operation of said printing mechanism, an auto print key for controlling said automatic means, a record supporting carriage, a carriage return key, a carriage return mechanism normally operated by said key, means for disabling said key during automatic typing operation, and means under control of said auto print key for initiating operation of said return mechanism.

6. The invention set forth in claim 5 including means operated by said carriage in the extreme right position, and means controlled by said car-

riage operated means for disabling said return mechanism.

7. The invention set forth in claim 5 including an adjustable means operated by said carriage in a predetermined escaped position, means under control of said auto print key for making said adjustable means effective, and means under control of said adjustable means for operating said return mechanism.

10. 8. In a carriage escapement device, an indenting stop, means for adjusting said stop, a carriage for a record sheet, an abutment slide for cooperating with said stop, means for selectively bringing said slide against said stop, an escapement means for said carriage including a movable member cooperating with said slide but held withdrawn therefrom, and means for releasing said escapement means and member to provide carriage movement as controlled by differential movement of said member in cooperating with said abutment slide.

15. 9. In a typewriter with a set of character keys and a shift key, a pair of wedges on each character key, said wedges being of a thickness proportioned according to the related upper and lower case type characters, said wedges being mounted with their operating sides parallel to the sides of the keys, a carriage escapement mechanism governed by said wedges and having a cam bar cooperating therewith, said bar movable and operable at right angles to the wedge sides and at right angles to the planes in which the keys are moved, movable mounting means for said bar, and means for selectively positioning said mounting means and bar in cooperation with upper or lower case wedges.

20. 10. In a printing machine, a set of printing members with upper and lower case character types, means for operating said members, means for controlling the operating means, means for shifting said members for upper case printing, a shift lock key, a shift release key, record sheet letter spacing mechanism, said mechanism including variable controls for upper and lower case printing, means for selecting one or the other of said variable controls, an electrical control device for said selecting means, a relay operated by said shift lock key and controlling the effectiveness of said electrical device to vary spacing, a holding circuit for said relay, and contacts in said circuit which are opened by said shift release key to restore said selecting means for normal spacing control.

25. 11. In an automatic typewriter having a set of type members, a series of operating keys and operating mechanism between the keys and the type members for controlling printing, the combination of means for setting a desired length of line, perforating mechanism for punching a tape under control of said keys to represent a complete line of letters arranged in word groups, a space indicating means controlled by the keys to disclose the amount of space required by the selected words, means for counting the number of words represented on the tape, means for detecting the difference between the predetermined length of line and the length of line ordinarily required by the selected words, a carriage mechanism carrying a platen and a worksheet, escapement mechanism cooperating therewith, word spacing devices operated under control of said word counting means and said line length detecting means for proportioning the spaces between words to justify the printed line, and means under control of said perforated tape for operating

said type operating mechanism to record the selected words automatically.

12. The invention set forth in claim 11, including type members having book face type of varying widths and a variable letter spacing mechanism cooperating with said escapement mechanism and controlled by the type operating mechanism.

13. The invention set forth in claim 11, including holding means for receiving one of a series of interchangeable type baskets readily removable from said machine to change from one font of type members to another font, and holding devices for receiving one of a series of removable letter spacing control bars cooperating with said escapement mechanism and said type operating mechanism and related to the type of the basket held.

14. In a typewriter, a set of printing levers, operating mechanism with a set of operating keys for controlling operation of said levers, a platen for holding a record sheet for cooperation with said levers, a carriage supporting said platen, an escapement mechanism cooperating with said carriage to control letter spacing, said mechanism including a stop member adjustable to an infinite variety of positions, and connections between said member and a series of spacing control blocks secured to the various keys, said blocks being proportioned to adjust said member to an extent related to the width of the type face on the lever selectively operated by the key.

15. The invention set forth in claim 14 including a storing means for partaking of and accumulating the movements of said adjustable member, line length determining means including means settable for coaction with said storing means in different positions of the latter, means to impart an end space measuring movement to said storing means to bring the same into coaction with said settable means, means to measure said last mentioned movement of said storing means, and means under control of said measuring means and cooperating with said escapement mechanism to determine word spacing for justifying a line of words or word parts to a predetermined length.

16. The invention set forth in claim 14, including a storing device cooperating with said adjustable member, said storing device including a pair of adjustable elements, one of which is maintained in constant cooperation with said member and the other of which is advanced in one direction a distance which is the accumulation of all spacing movements of said member, and a pair of clutches between said device and said elements for holding and releasing said elements in synchronism with the advancing and retracting movements of said member and said device, and means cooperating with said storing device and the escapement mechanism to determine the length of spacing escapement.

17. In a key controlled machine, a set of control keys, a set of key release combs with teeth for releasing and locking said keys, means for setting said combs to select a certain key, a set of springs attached to said keys, and means for tensioning said springs after operation of said setting means to operate said certain selected key.

18. In an automatic word spacing device controlled by a record, a face cam, means for setting said cam for justified word spacing, a carriage for a record sheet, an escapement means for said carriage including a movable slide cooperating with said cam, a fixed frame element, a clutch

for connecting said carriage to the slide and element alternately, and means under control of said record for operating said clutch alternately to allow carriage escapement as governed by said cam.

19. In a letter spacing control mechanism, a holder for a record sheet, a series of type members, a set of character and control keys for operating said members, a variable spacing control device including a member adjustable to an infinite variety of positions, an element movable from a normal position into engagement with said member, means operated by said keys to adjust the position of said member according to the width of the type selected by the key, a pair of clutching devices one for holding said holder in a fixed position and the other for connecting said holder to said element, means for operating said clutching devices so that the last mentioned device is engaged before the first mentioned device is disengaged, a spring for urging said holder to space in accordance with the setting of said member, and means for disabling said clutch operating means so that the clutch connection to the fixed device is restored before the clutch connection to said element is disabled.

20. In a record spacing device, a record holder, an escapement mechanism cooperating with said holder to space said record, an abutment member adjustable to an infinite variety of positions, means for adjusting said member to select the extent of spacing, a spacing control means between said member and said mechanism to partake of its adjustment, a clutch mechanism between said control means and said mechanism, a series of keys for operating said member differentially, and means under control of an operated key for operating said clutch mechanism, whereby the record is spaced differently by different keys.

21. The invention set forth in claim 20 including a clamping means for holding said member in an adjusted position, and means under control of said clutch operating means for controlling the operation of said clamping means.

22. In a justifying mechanism, a set of character selection keys, a letter space control means, means under control of said keys for operating said means differentially, a justification control bar slidably mounted with respect to said space control means, a fixed member, a double acting clamp device for clamping said bar to said space control means and to said member alternately to advance said bar an extent accumulative of the operations of the letter space means, and means under control of said keys for operating said clamp device.

23. The invention set forth in claim 22, including a second control bar mounted and controlled as the first mentioned bar, a settable stop for a predetermined line length, additional devices for operating said second bar to draw it against said stop through a length of unused line length, and means under control of said additional devices for controlling justification.

24. The invention set forth in claim 22, including a settable stop for determining a justified line length, means for moving said bar independent of key action to abut against said stop and measure unused line length, a setting means controlled by said bar and carried through the distance of said unused line length, a word counting means operated by a space key, a member on said setting means and adjusted by said word counting means, and justification space selection controls operated

under control of said member to select justified spacing according to the number of words and amount of preliminary unused line length in a line.

25. The invention set forth in claim 22, including a spacing key, means for restoring said bar, and means under control of said spacing means for initiating operation of said restoring means.

26. The invention set forth in claim 22, including a second bar moved for letter spacing, a clamp device for said second bar, a spacing key, a pair of restoring means for said bars, means under control of said key for initiating operation of the clamp device for the first mentioned bar and the restoring means for the second bar, and means for initiating operation of the restoring means for the first mentioned bar.

27. In an automatic printing machine, a series of type members, a platen, a carriage supporting said platen, carriage escapement controls, a series of operating keys related to said type members, connections between said keys and type members including an automatic operating means, a program device, a pair of sensing devices cooperating with said program device, means for selecting the first of said sensing devices and simultaneously disabling said key connections, means under control of said program device and said first sensing device for operating said keys in sequence to select a series of words composing one line of print to be justified, a justification mechanism cooperating with said escapement controls, a line length determining means, means under control of the operated keys for setting the justification mechanism according to the various letter spaces, the number of word spaces and the length of unused line spaces as predetermined by said line determining means, means for discontinuing operation under control of the first sensing device and initiating printing control under control of the second sensing device, means for moving said sensing devices relative to said program device, means for restoring said key connections, and means under control of said second sensing device in cooperation with said justification mechanism for causing a series of operations of said keys and type members along with carriage escapement to effect printing of a predetermined series of words in a predetermined length of line.

28. In a perforating and printing machine, a series of keys including character and sign representing keys and function control keys such as shifting lock, shift release, indent, space, back space, carriage return, and automatic print keys, a set of six code bars underlying said series of keys, said bars having cam formations so that one or more of the bars is shifted in combination under control of an operated key, contacts closed by the shifted bars, a series of six punches cooperating with a control tape, a set of six electrical controls for operating said punches individually, wiring connections from each of said electrical controls to each of said contacts, whereby a combination of perforations is represented on the tape for each key operation, means for sensing successive combinations of perforations on a tape so produced, a set of electrical devices controlled by said sensing means for automatically operating said keys, a pair of contacts in series with said electrical devices, a common bail operated by said punches, and means under control of said bail for opening said contacts to release said keys in readiness for another operation.

29. In a perforating and printing machine, a

set of data selection keys, adjustable devices set under control of said keys, a perforating mechanism operated under control of said devices to punch a record of operated keys, a printing mechanism operated by said keys, means under control of said record for setting said adjustable devices, and means cooperating with said setting means for operating said keys and printing mechanism to print a record of the data stored on the record.

30. The invention set forth in claim 29, wherein in said adjustable devices include a set of code bars for operating punch selecting contacts and subject to operation by record selected magnets.

31. In a printing machine, a set of character printing control keys, a perforating mechanism, a set of code bars operated in combination by said keys, means under control of said bars for controlling said perforating mechanism, means for locking said keys in either operated or normal positions, an electrical means controlled by the actuation of any key for operating said locking means, contacts in series with said electrical means, and means under control of said mechanism for opening said contacts to release an operated key after perforating is performed.

32. In a printing machine, a series of type levers, a platen, a carriage supporting said platen, carriage spacing mechanism, a set of operating keys related to said type levers, operating mechanism for said type levers, normally effective connections between said keys and the operating mechanism related thereto, means for disabling said connections for a series of operations of said keys for control of justification, justification control devices cooperating with said spacing mechanism and including a series of letter space blocks secured to said keys and proportioned in accordance with the type width related thereto, a line length setting means for predetermining justified line length, a shiftable justification control bar cooperating with said blocks and cammed thereby, justification control mechanism adjusted by said bar according to the total letter space widths selected and also controlled according to the number of word spaces selected by a space key, said controls also influenced by said setting means and the length of unused space left after the last letter spacing operation, a printing control mechanism designed to be operated by a second sequence of operation of said keys and comprising means for making said connections between said keys and the operating mechanism effective, and means for calling said justification controls into operation as an incident to each word spacing selection to shift the carriage so that the end of the printed line coincides with a predetermined point, whereby a predetermined length of book type printing is realized as a result of two sequences of similar key operation, the first series of operation selecting a justification factor and the second series of operation causing printing and spacing influenced by said justification factor.

33. In a page printing machine, a series of type levers with book face type, a platen, a carriage for the platen, escapement mechanism for the carriage, operating mechanism for said levers, a set of operating keys for connecting said levers to said operating mechanism, each of said keys being related to one of said levers, each key carrying a pair of justification control blocks proportioned in accordance with the width of the upper and lower case characters on the related type lever, a letter spacing control bar cooper-

ating with said blocks and normally in the path of the blocks related to the lower case type, means cooperating with said bar for partaking in and retaining the movement thereof, means for adjusting a predetermined length of line, word spacing control means, Justification controls called into operation after key operation relating to one line and varied according to the number of word spacing operations in the line and the unused space determined by the line length, setting means for predetermined word spacing for justified printing, a series of code bars cooperating with all the keys, one or more of said bars being adjusted in a code combination by the operation of a key, contacts closed by operated bars, a punching mechanism cooperating with a record tape, punch magnets controlling operation of said mechanism, said magnets wired in series with said contacts, means for feeding said tape under control of said keys, tape sensing means, means for disabling said sensing means during operation of said keys for justification control, an automatic print means for disabling

10 said punching mechanism and selecting operation of said justification controls and operation of said sensing means for control of justified printing, electrical shifting means cooperating with said code bars, means under control of said tape sensing means for operating certain of said electrical controls for shifting said bars to select certain keys, means for automatically operating the tape selected keys successively, means for disabling the control of said keys over said type levers during the operation of said punching mechanism to punch the representation of a line of words on the tape and for enabling said control during the automatic operation of said keys under control of the tape sensing means, means under control of said justification controls and cooperating with said escapement mechanism for permitting escape of said carriage a predetermined distance for word spacing during automatic printing, carriage return devices, and means for operating said devices at the end of the line after automatic typing operation.

WALDEMAR A. AYRES.
